ABSTRACT OF THE DISCLOSURE

A machine for the centrifugal casting of pipe having four groups of molds mounted around the periphery of a rotatable turret. Also disposed around the turret on either end thereof are four operating stations located around the periphery of the turret so as to register with the mold groups at one time. During a casting cycle each of the mold groups is successively brought into registry with different ones of the stations by rotation of the turret. At the first station the molds are rapidly spun, cleaned and then sprayed with a refractory lining. At the second station the molds receive a lined mandrel at one of their ends, are again rapidly spun, and molten metal is then poured into the other end of the spinning, coated molds to form the casting. Next the turret is indexed to position the molds with the molten metal in them at the third station where a high pressure jet of cooling fluid is forced through the inside of the castings to cool and solidify them. Finally, the turret is indexed to bring the mold group with the solidified casting in them to the fourth station where the castings are extracted from the mold by means of expandable tongs mounted on a retractable carriage. During the first three steps of lining, pouring, and cooling, the molds are cooled by a cooling system located within the turret which directs a spray of coolant at the molds while they are in the coating, pouring, and cooling stations. This cooling is under the control of mold temperature sensors in order to help maintain the temperature of the molds within a limited range. There is also provided a cooling system at the cooling station for rapidly cooling the cast metal pipe without chilling it.

This application is a continuation-in-part of prior pending application Ser. No. 313,389, filed on Oct. 2, 1963, now abandoned, and relates generally to the centrifugal casting of pipe, and more particularly to method and apparatus for the automatic high speed casting of such pipe.

In the manufacture of cast iron pipe, the use of centrifugally spun molds is a common expedient. In recent years molds have been lined with a refractory lining prior to receiving a charge of molten metal. Thus the steps commonly followed in the manufacture of cast pipes include the lining of a mold, the pouring of metal into the mold, and the extraction of the solidified metal from the mold.

Various machines have been designed and put into use for reducing the amount of labor required to perform the casting process. In some machines molds are rotatably mounted around the periphery of a turret and the turret is indexed so as to bring the molds into alignment with a pouring station and an extracting station. In some machines cooling sprays are directed at the molds to reduce the temperature rise to which they are subjected by the molten metal. Still other machines have included means for semi-automatically carrying out the mold lining step of the casting operation.

Although several of the machines used for centrifugal

2

casting of tubular articles automate certain steps in the casting process, none of them is fully automatic. Further, those machines which incorporate means for cooling either the mold or the cast metal within the mold have no means for preventing chilling of the cast metal as a result of the cooling, thus necessitating the annealing of the cast tubular article after it has been cooled.

It is therefore an object of this invention to provide a method and apparatus for performing all of the steps in the manufacture of centrifugally cast pipe continuously and automatically with a minimum of human intervention.

A related object of this invention is the provision of a method and apparatus for continuously and automatically 15 coating a permanent mold with a refractory lining of predetermined thermal characteristics, pouring a predetermined amount of metal into the coated mold while spinning the mold, then cooling the mold and the cast metal within it without chilling the metal and finally extracting the solidified and cooled metal pipe from the mold.

Another object of this invention is to prolong the useful life of the mold by maintaining it within a predetermined temperature range during each step of the casting cycle. 25 A related object of the invention is to maintain a uniform temperature along the length of the mold during every step of the casting cycle.

Yet another object of the invention is to increase the speed at which poured metal may be cooled in the mold by cooling said metal at a high rate before the metal has solidified and by cooling the metal at a lower rate thereafter. A more specific and related object of the invention is to adjust the rate of cooling of the metal immediately after it has been poured, to a level which would chill the metal excessively if continued after the metal froze, and to automatically reduce the rate of cooling after the cast metal has given up some but not all of its latent heat of fusion to a level which will not cause excessive chilling of the metal.

It is yet another object of the invention to predetermine the temperature at which the molten metal shall freeze in the molds and give up its latent heat of fusion so as to permit more reliable sensing of this temperature for controlling the cooling of the metal. It is a related and more specific object of this invention automatically to regulate the composition of the metal which is poured into the mold so as to assure that the metal will freeze at a single well-defined temperature.

Another important object of the invention is to speed up the production of iron castings by standardizing the carbon equivalent of the cast metal through late inoculation so as to improve nucleation of the metal and so as to predetermine the temperature at which the metal shall freeze. A related and more specific object of the invention is to standardize the carbon equivalent of the iron that is poured into the mold at a level at which the metal is eutectic thereby to impart to the metal a single freezing temperature.

60 A further object of the invention is to provide a self-correcting gripper for removing a finished casting from its mold automatically, the gripper having the ability to automatically re-establish its hold on the casting in the event that the gripper should lose its hold.

65 It is another object of the invention to provide an improved centrifugal casting apparatus which permits the use of highly conductive permanent metal molds which are mechanically lined with a uniform layer of good quality refractory material prior to casting, with the refractory material being removed and reused after each casting cycle.

A related object of the invention is to provide improved pipe casting apparatus whereby the bell portion of the pipe is cast with the body thereof, thus eliminating a heretofore necessary extra step.

These and other objects and advantages of the invention will become apparent from a further reading of the following detailed description taken in conjunction with the appended drawings wherein:

FIGURE 1 is a side elevation of a machine embodying the structural aspects of the present invention;

FIG. 2 is an elevation of the FIGURE 1 machine viewed from its right end;

While the invention is susceptible of various modifications and alternative constructions, a particular embodiment has been shown in the drawings and will be described below in appreciable detail. It should be understood, however, that there is no intention to limit the invention to the specific form disclosed, but rather the intention is to cover all modifications, alternative constructions and equivalents falling within the spirit and scope of the invention as expressed in the appended claims.

With more particular reference now of the drawings, a machine is illustrated therein which is constructed in accordance with the present invention and which is adapted in the embodiment shown to cast pipe centrifugally through a series of integrated wholly automatic operations sequentially timed and performed on permanent molds rotatably disposed in a turret which is indexed through various operative stations.

The operations required to cast pipe, or articles of a similar nature contemplated by the invention, includes cleaning and lining the molds with a refractory material, pouring and evenly distributing the desired quantity of molten material within the molds, cooling the casing and removing the same. As indicated, the present invention

contemplates the complete casting of such pipe from beginning to end by provision of the various operative machine elements spaced about the peripheral area of the mold turret as will now be detailed.

PREAMBLE

In order to facilitate the understanding of the machine which is illustrated herein, there will first be described the structure of the machine so as to highlight those features of the invention which reside therein. There will then be described that system of the apparatus which control the composition of the metal which is poured into castings and those systems which control the temperature of the mold and of the cast metal within the apparatus so as to explain most clearly those features of the invention which reside in these systems. Finally, there will be described a hydraulic and electrical control system whereby all machine operations are carried out continuously and automatically with substantially no human intervention.

A. STRUCTURAL ARRANGEMENT AND OPERATION OF A MACHINE INCORPORATING FEATURES OF THE INVENTION

(1) In general

An exemplary machine constructed in accordance with the present invention for the centrifugal casting of pipe is illustrated in FIG. 1 at 15. The machine has four groups of molds mounted around the periphery of a rotatable turret. Also disposed around the turret on either end thereof are four operating stations located around the periphery of the turret so as to register with the mold groups at one time. During a casting cycle, each of the mold groups is successively brought into registry with different ones of the stations by rotation of the turret.

At the first station, the molds are rapidly spun around their longitudinal axes, cleaned and then sprayed with a refractory lining. At the second station the molds receive a lined mandrel at one of their ends, are again rapidly spun, and molten metal is then poured into the other end of the spinning, coated molds to form the casting. Next, the turret is indexed to position the molds with the molten metal in them at the third station where a high pressure jet of cooling fluid is forced through the inside of the castings to cool and solidify them. Finally, the turret is indexed to bring the mold group with the solidified castings in them to the fourth station where the castings are extracted from the molds by means of expandable tongs mounted on a retractable carriage.

During the first three steps of lining, pouring, and cooling, the molds are cooled by a cooling system located within the turret which directs a spray of coolant at the molds while they are in the coating, pouring and cooling stations. Through this expedient, the temperature rise to which the molds are subjected is limited, thus extending their useful life.

(2) In detail

(a) The turret.—The machine 15 comprises a cylindrical turret 17 mounted for rotation on a horizontal axis supported by a machine framework identified at 19. Reference will be had to FIGS. 2 and 3 for a more complete picture of this framework.

The turret is positioned within the framework and supported about its circumference for rotation by means of rollers 21, secured to the frame 19 by mounting blocks 22 and spaced about the periphery of the turret 17 to provide optimum rotational freedom therefor. As will be seen in FIG. 1, the rollers engage the periphery of the turret 17 in tracks defined by spaced ribs 23, to inhibit any tendency toward axial displacement of the turret. In order to rotate the turret, a power drive is provided in the form of an electric motor 25 having a toothed pinion 26 attached to the armature thereof. A ring gear 28 is fixed to the turret about its perimeter where it is engaged by the pinion 26 to complete the turret drive.

With reference now to FIGS. 4, 6 and 7, the turret 17 carries a plurality of cylindrical molds 32. The molds 32 extend on a horizontal axis through the turret, and in order to increase productivity of the machine, the molds are conveniently grouped within the turret about its periphery in multiples of two molds per group. The size of the group may be varied, however, without departing from the invention.

The molds are supported within the turret shell by means of front and rear cover plates 34, 35. The cover plates 34-35 are formed with holes 37 (see particularly FIG. 7) which receive roller bearings 38 for supporting the molds front and rear. The bearings 38 engage a raised collar portion 40, formed for the purpose, on the molds 32, thus permitting the molds to be spun within the rotating turret in the performance of the various operations required for the casting of pipe or like material.

(b) The lining station.—In any casting process where a permanent mold is to be employed, it is desirable in order to preserve the mold to control the cooling of the cast article, and to provide a smooth finish thereon to line the mold with a refractory material of a fine particulate material which presents a smooth surface of determinable heat conductivity to the molten material to be cast. In carrying out the present invention, the molds 32 are provided with a refractory lining 43 of controlled material consistency and thickness, automatically in response to the arrival of a group of unlined molds at a "lining station."

The automatic refractory lining function of the machine is illustrated in FIG. 6, supplemented by FIGS. 1 and 3. Upon arriving in the lining station, the mold 32 is spun by motor MTR5 through its spinner disk 42. A refractory lining is applied under pressure in particulate form to the inner wall of the mold 32. To this end, a spray nozzle arrangement, indicated generally as 45 in FIG. 6, is provided at the "lining station." The nozzle assembly comprises a pair of concentric nozzles, one of which, nozzle 47, applies the refractory material, and the second nozzle 48, applies a resin binder.

The nozzle 47 is connected at one end to a hopper 50 which is filled with the refractory material to be applied. A slide 52 is provided with an aperture 53 therein to provide control over the flow of refractory material into the nozzle body. A converging air horn 55 is located in the rear of the nozzle, behind its throat, and is connected to a pressure source through hose 57. Thus, by applying air pressure through hose 57 the refractory material is drawn into the air flow stream and is ejected from the nozzle under pressure against a guide disc 59 which fits about the body of the nozzle 48 and deflects the refractory material outwardly in a conical path against the inner wall of the mold 32.

The present invention contemplates the individual application of refractory material and binder to permit easier handling of both. The nozzle 48, as previously indicated, projects a liquid resin binder into the conical path of the refractory material as it is sprayed on the wall of the mold 32. In this manner, a mixture of binder and refractory material hits the wall under pressure to form a refractory lining of controlled thickness. Thus, binder material under pressure and in controlled proportion is forced into the nozzle 48 through a hose 63 and against a conical guide 65 formed on or otherwise secured to a control rod 67 mounted in the nozzle 48 and, in the present instance, passing through the rear wall thereof where a nut 68 is provided for convenient coarse adjustment of binder flow from the nozzle by positioning of the conical guide 65 with respect to the end thereof.

In order that a lining of uniform thickness may be provided over the entire length of the mold, the spray nozzle arrangement is preferably mounted on a carriage 70. Since two molds are provided in a group, a pair of spray nozzles are provided to operate in unison, and as seen in FIG. 1, a pair of carriages 70 are provided, and move on a track 72 having an axis parallel to the axis of the molds at the

station and so positioned that the nozzles are concentric with the mold axes as indicated in FIG. 6. Thus, as the lining operation is signalled into activity by arrival of the bare molds, pressure is applied to the refractory lining material while at the same time liquid binder is forced into the path of the refractory material ejected from the nozzle and the carriages 70 begin to move at a controlled rate to the right as seen in FIG. 1 extending the nozzle end into the mold and, by moving at the desired rate, effecting a uniform application of binder and refractory material against the mold interior. Actual movement of the carriage may be conveniently controlled hydraulically and such an arrangement will be described in more detail hereinafter.

The lining 43 is quickly cured by the heat of the mold which has completed a cycle previously and which is at a temperature of about 350° F. The molds are then ready for pouring.

(c) The pouring station.—Having prepared a pair of molds in a group by lining them, the turret is indexed, in this instance in a counterclockwise direction as indicated in FIG. 3, to bring the lined pair of molds to a pouring station where a predetermined quantity of molten material is applied to their interiors. As seen in FIGURE 1, the pouring station is indicated generally at 80 and includes a storage cauldron 82 adapted to pour a quantity of molten material into a measuring and pouring bucket or ladle 84 mounted on a swing frame 85 to permit dumping of the contents of bucket 84 into a pouring horn 87 mounted adjacent the end of the mold 32. The pouring ladle 84 and the pouring horn 87 rest on the platform 88 of a measuring scale 89. Again, two molds are presented at the pouring station and while the description has been keyed to the pouring of one mold, it will be appreciated that simultaneous pouring of both molds is undertaken by identical equipment.

As above indicated, the molds 32 are mounted for rotation within the turret and, in order to accomplish uniform centrifugal casting of the pipe for which the present machine is adapted, the molds in the pouring station are spun on their axes within the turret to effect uniform distribution of the molten material throughout the mold.

To this end, it will be noted in FIG. 8 that the ends of each mold are provided with a removable spin band 90 which comprises an enlarged flanged head which is screwed onto the end of the mold and secured by a locking bolt 92. The spin bands frictionally engage power drives at the various stations where such drives are provided for spinning the molds. Such a power drive is present at the pouring station and is indicated generally at 95 in FIGURE 1. A main drive motor 97, preferably providing variable speed control, is supported on a vertically movable platform 98 which is connected to elevating cylinders 100. The motor 97 is connected at their side through couplings 102 to shafts 103, which are supported in pillow blocks 104, and through the shafts 103 to drive wheels 105. The wheels 105 engage drive belts 107 mounted about smaller driven wheels 109 supported on the frame 10. In order to permit optimum control over acceleration and deceleration of the molds, the wheels 105 and belts 107 may be toothed to provide a nonslip driving connection. The wheels 109 are mounted for driving spinners 111 which are engageable with the spin bands 90 of the molds by elevating the platform 98 to provide the desired engagement. Once engaged, the molds are spun at a controlled speed, causing the molten material to be spread out and to be uniformly distributed within the mold to form a pipe of uniform thickness and density.

(d) The cooling station.—Having poured the molds, the turret is again indexed counterclockwise to bring them to the cooling station where heat is extracted from the material in a manner to provide a pipe which does not contain heat stresses and which does not require further annealing after the casting has been completed.

It is in keeping with this aspect of the invention that cooling is controlled to avoid chilling the metal. To the end of providing an efficient controlled cooling system, a pressure spray arrangement is provided at 210, and comprises a pair of nozzles 212 aligned with the axes of the molds 32 at the cooling station. The nozzles are connected by conduit 214 to a source of coolant under pressure, which may be water.

Upon arrival of the molds at the cooling station, a mold cross section has the appearance of the cross section indicated in FIG. 5 with an inner solidified object 41, such as pipe, against an intermediate layer of refractory material 43 bonded on the wall of the mold 32. The arrival of the molds triggers the application of a spray of coolant against the inner surface of the molded pipe 41. The pressure of the coolant is sufficiently high so that a vapor blanket is not permitted to form between the wall of the hot molded object and the coolant spray, which would have an insulating effect which would interfere with optimum cooling. Instead, vapor is forced toward the opposite end of the mold by the high pressure spray where a ventilator hood 116 is provided over the end of the mold opposite the spray nozzle 212. An exhaust fan (not shown) may be provided in the exhaust conduit 117 which carries the vapor formed in the molds away, thus permitting continuous contact of the fine spray of coolant material with the molded object.

A novel control system for regulating the application of coolant through the spray nozzles to the cast pipe in the molds so as to control the rate at which heat is carried away from the pipes by the coolant is described in Sections B1b and B2b of the specification.

The refractory material permits a predetermined amount of heat flow between the molded pipe and the mold thereby causing an amount of heat to be dissipated in that direction, and the present invention also provides for controlled dissipation of heat through the permanent mold. A mold cooling system for providing continuous and precise thermostatic control over the temperature of molds at the lining, pouring, and cooling stations is described in Sections B1a and B2a of the application.

By way of a brief introduction, to acquaint the reader with the physical location of this cooling system in the casting machine, reference is here made to FIG. 4, a cross section of the turret which illustrates the mold cooling system of my invention. Controlled dissipation of heat through the molds 32 is achieved by means of a spray system 120 comprising a number of multi-nozzle spray heads 122a-f positioned at each of the lining, pouring, and cooling stations. Each spray head 122 is provided with a series of nozzles 128 spaced along the length of the molds 32. Each set of nozzles is connected by conduit 124 to a central source of fluid pressure 125 through a valve 126.

Since it is the objective of the system 120 to provide a predetermined uniform temperature gradient through the mold, sensory controls are provided to determine the heat dissipation from the mold and control coolant spray. To this end, infrared sensory devices 127a-f are provided close to the mold surface at positions along the length of the mold and at the various stations where spray nozzles 122 are provided. The sensor 127 are highly sensitive to temperature and each sensor is connected to the valve 126 for the particular set of nozzles associated with it to vary the flow from that set of nozzles to maintain the temperature along each mold uniform so as to provide optimum cooling of the pipe within the molds.

Since heat transfer in the mold is primarily by conduction of heat energy through the refractory lining and wall of the metal mold, a measure of control over the temperature gradient may be established by correctly proportioning the thickness of the metal mold wall and liner to the pipe wall thickness to be cast. A typical proportion is represented by the FIG. 5 cross section.

Because of the close control that is exercised over heat dissipation, the molds may be suitably constructed of

beryllium copper, and will possess a longevity of usefulness heretofore unknown in an automatic operation.

(e) The pipe extracting and mold cleaning station.—The cast pipe having solidified and cooled to a temperature at which the pipe can be handled for removal from the mold, the turret is again indexed and the cast pipe moved to an extractor station indicated generally at 130. It is in keeping with the objectives of the present invention that the pipe is automatically removed from the molds thereby completing the casting of the pipe from beginning to end in a completely automatic fashion.

Referring to FIGS. 1 and 3, removal of the pipe is accomplished by engaging the interior of the pipe with an expandable gripping device indicated at 132. As shown, the gripper device is hydraulically operated and comprises expandable grippers or tongs 134 extending from a hydraulic cylinder 136 which is mounted on a carriage 138. The carriage is driven on a track 140 in a direction toward and away from the mold and in axial alignment therewith. Upon arrival of a mold containing a cast pipe, the carriage 138 is signalled to operate and travels forward toward the mold, inserting the grippers 134 into the interior of the mold where they are expanded by the automatic hydraulic cylinder to engage securely the inner wall of the cast pipe. Once engaged with the pipe, the carriage reverses and retreats on the track 140, thus drawing the pipe from the mold. It is an additional feature of the invention that in the event that the grippers 134 should disengage for any reason, the extractor will automatically return the grippers 134 to the interior of the pipe which is partially removed and continue the removal process by engaging the pipe and causing the carriage again to retreat. To accomplish this, a sensing device is provided on the carriage such as, for example, an infrared sensor 142 which is focused on the gripper 134 and is connected with the carriage control so that if the carriage begins to retract without the pipe, the sensor will so indicate to the control and the carriage and grippers will be returned to pick up the pipe and continue the removal thereof. The control circuit for accomplishing automatic operation of the grippers and their carriages in response to the heat sensors is further explained in Section C of the specification.

Again, since two molds are presented at the extractor station at a time, two extracting devices are provided although one has been described for the purpose of explanation.

Once the cast pipe has been removed from the molds, the molds are again ready to receive a refractory lining and repeat the process. Before this can happen, however, the refractory material presently in the finished mold must be removed and the mold cleaned in order that it may satisfactorily receive the new lining. It will be understood that the binder has been consumed by the heat of the molten material, and pure refractory material remains, being held against the mold by the carbon bond of the burnt-out binder. It is an attribute of the present invention that the refractory material may be removed and reclaimed to be again used in the lining process. Thus, a very excellent and initially expensive material such as zircon or granulated carbon may be used, and reused, without undue expense.

In accomplishing the cleaning and reclamation of the used refractory material, a pair of powered, extensible rotary wire brushes are provided at the lining station, opposite the nozzle system 45. Thus, brushes 150 are provided on shafts 152 which are aligned with the axes of the molds at the lining station. The brushes are mounted on carriages 155 which ride on a rail 157 to and from the mold. The brushes are rotated in any convenient manner such as by air motors provided on the carriage indicated generally at 159 and are traversed into the mold toward the end at which nozzles 45 are disposed.

Referring particularly to FIG. 6, a recovery trough 162 is provided at the ends of the mold and the refractory

material which is brushed from the interior of the mold and pushed ahead of the brush as the brush traverses the mold, is dumped into the trough 162 where it is returned by an appropriate conveyor system (not shown) to the hopper for reuse. Generally, one pass of the brushes 150 will be sufficient and the brushes will retract upon completion of the traverse and will signal the nozzles 45 to begin applying a fresh refractory lining to the mold.

(f) The bell molding apparatus.—It is still another feature of the present invention that in the casting of socket pipe or the like, the bell end socket of the pipe may be cast simultaneously with the casting of the pipe by means of refractory coated bell end cores rather than requiring that it be cast by means of refractory head cores produced on separate head core making machines and set in the pipe molds prior to each casting cycle.

Referring to FIGS. 1 and 7, an automatic bell forming arrangement is provided and indicated generally at 180°. The bell forming apparatus comprises in the present instance, two groups of bell end cores 182, 184 mounted on an indexable turret plate 186 secured and positioned on a frame 188. The bell forming apparatus 180 is so constructed as to permit one group of cores to be engaged with the ends of the molds 32 at the casting station for casting purposes while at the same time the other group of cores is being prepared with a refractory lining in a liner cabinet 190.

Thus, referring particularly to FIG. 7, the cores 182 and 184 are extended respectively into the end of a mold 32 and the liner cabinet 190. In the former, the refractory coated core 182 closes the end of the mold 32 at the casting station and the molten material being spun into the mold passes into the bell forming end where that end is cast automatically with the pipe.

At the same time, in the lining cabinet a plurality of heating burners 196, are directed against split metal molds 191 into which the bell end cores are inserted and refractory lining identical to that applied to the mold walls is applied thereto through an extruder 195. The heating burners 196, maintain a resin curing temperature at the bell end cores in order to bond the refractory lining thereto. Once the casting operation is completed, the used bell end cores with the refractory lining burned off are retracted and indexed, so that the prepared set of bell cores are now in position to be inserted into the ends of the new molds which have just arrived from the mold lining station of the turret. The prepared sets are then applied to the prepared molds for casting while the used set is being relined.

It will be appreciated that while a number of operations are involved in the casting of pipe as herein described, these operations are performed concurrently at the several stations, the time required for each operation being programmed to be approximately the same so as to permit the turret to be indexed at uniform intervals. By performing several operations concurrently, the speed and economy with which pipe can be cast is greatly increased.

B. TEMPERATURE AND COMPOSITION CONTROL SYSTEM

(1) The mold cooling system

The cooling system for maintaining the temperatures of the molds 32 in the turret 17 within prescribed temperature limits is generally shown in FIG. 9. The turret 17 is shown in phantom outline form and within the turret, distributed around the periphery thereof are shown the eight molds 32. Two molds 32 are shown at each of the coating stations A and B, pouring stations C and D, cooling stations E and F, and extracting stations G and H. For sake of clarity, only three of the eight molds, one at coating station B, one at pouring station D, and one at cooling station F are shown in solid lines, the remaining five molds being shown in phantom outline form only.

Each of the six molds 32 located at the coating, pouring, and cooling stations is cooled by a plurality of multi-

nozzle spray heads 122. Of the six sets of spray heads 122 which are used to cool the six molds 32, only three sets, associated with the molds shown in solid lines appear within FIG. 9. FIG. 13 shows a complete mold cooling system for the cooling stations E and F, and the mold cooling systems at the coating and pouring stations are similarly arranged.

The amount of cooling required to maintain the molds at the different stations at a given temperature various considerably. As one example it will be realized that this rate will be much higher at the pouring station where the molds receive iron at about 2400° F. than at the coating station which receives molds only slightly in excess of the desired temperature. Accordingly, means are provided for individually cooling each mold in the coating, pouring, and cooling stations.

It will also be realized that the rate at which cooling tends to occur is not the same along the length of the turret. Accordingly, in order to avoid variations in the temperature of the molds along their length, means are also provided to effect cooling of the molds in separate zones with the rate of cooling of each zone being governed by the temperature of the mold in that zone. In keeping with this general feature of the invention, the turret 17 is divided into three zones and within each zone coolant is applied at a mold 32 through a multi-nozzle spray head 122 (FIGS. 9 and 13). Thus zones 1, 2, and 3 of the mold 32 appearing in the coating station B are cooled by spray heads 122b1, 122b2, and 122b3 respectively. Similarly, mold 32 appearing in the pouring station D is cooled by spray heads 122d1, 122d2, and 122d3.

To afford individual control over the temperature of each mold, and for each of the molds individual control over each of its three zones, a separate sub-system is provided for controlling the flow of coolant through each individual spray head 122. Thus a set of three coating station mold temperature controls 200b are provided for controlling the flow of coolant through spray heads 122b1, 122b2, and 122b3 (FIG. 9). A second set of controls 200d are provided for controlling the passage of coolant through spray heads associated with the pouring station D and a third set of controls 200f are provided for controlling the spray heads in the cooling station F. Since there is one temperature control 200 for each spray head 122, there are six temperature controls for each of the three stations (FIG. 13); there are in all eighteen temperature controls associated with the eighteen spray heads located in the coating, pouring, and cooling stations of the turret 17. However, since only half of the eighteen spray heads are shown in FIG. 9, similarly only half of the eighteen temperature controls 200 appear in FIG. 9.

Flow of coolant through each of the spray heads 122 is controlled by a solenoid operated valve 126 in response to the output of a temperature sensor 127. Taking as an example the system for cooling zone 1 of the mold 32 in cooling station F (FIG. 13), the surface temperature of the mold 32 in zone 1 is detected by temperature sensor 127f1 which generates a signal whose magnitude is a function of the temperature detected by the sensor 127f1. This signal is fed through line 202f1 to the coating station upper mold zone 1 temperature control 200f1. The temperature control is set to generate a voltage whenever the temperature detected by the detector 127f1 exceeds a pre-determined level. This signal is fed from the temperature control through line 204f1 to the control valve 126f1 causing the valve to open and to admit coolant to the spray head 122f1. This condition continues until the temperature of the upper mold in zone 1 drops below the preset level at which point the temperature control 200f1 ceases to send a signal to the valve 126f1 causing it to close and coolant to be cut off from the spray head 122f1.

Flow of coolant to the mold cooling spray heads 122f2 and 122f3 at the cooling station F is similarly regulated by valves 126f2 and 126f3 under the control of sections

2 and 3 of the cooling station mold temperature controls 200/2 and 200/3 in accordance with the temperatures of zones 2 and 3 of the mold 32 as detected by temperature sensors 127/2 and 127/3. Control over the cooling of each mold in the extracting stations A and B and in the pouring stations C and D is similarly accomplished in control systems such as those just described for the cooling stations E and F.

As a result of thermostatically controlled cooling of molds in each of the coating, pouring, and cooling stations, the exterior temperature of a mold as it is successively cycled through the different stations of the pipe casting apparatus is kept within well-defined limits thereby greatly prolonging the life of the molds.

The relatively slight changes to which a mold 32 is subjected through the four cycles of coating, pouring, cooling, and extracting is well shown in FIG. 11 which illustrates the temperature of a mold during its travel through the four stations, three of which are cooled by a cooling system set to turn on when the temperature of the mold surfaces exceeds 350° F.

The mold arrives in the coating station from the uncooled extracting station at a temperature which is slightly in excess of 350° F. As a result, the coating station spray heads are turned on and the mold exterior temperature is lowered throughout the cycle until the mold is indexed out of the coating station into the pouring station. As molten metal is poured into the mold, its temperature rises sharply, causing the pouring station mold temperature controls to initiate cooling of the mold. Thus cooled, the exterior temperature of the mold reaches only about 380° F. when the mold is indexed out of the pouring station into the cooling station.

Once in the cooling station, the exterior temperature of the mold drops under the combined action of the cooling station mold cooling sprays and the internal spray units 210. The action of the internal spray units 210 which will be described in detail hereinafter, is reflected in the reversal of the mold exterior temperature change at points B and C during the time that the mold is in the cooling station.

The mold is indexed out of the cooling station at a temperature slightly below the nominal temperature of 350° into the extracting station. In order to prevent seizing of the mold around the pipe within it, molds are not cooled in the extracting station and as a result the mold exterior temperature rises in this station to a point slightly above the nominal temperature of 350° for which the mold temperature controls 200 are set.

(2) The internal cooling system

In the use of a multi-station automatic pipe casting machine of the type described, it has been observed that the speed at which the machine is operable can be greatly improved by increasing the rate at which poured metal is cooled at the cooling station. In this connection, it is particularly significant that since the mold groups around the periphery of the turret are indexed from station to station at the same time, indexing of the molds cannot occur until the slowest of the four operations has been completed. Of the four operations of coating, pouring, cooling, and extracting, quite often the cooling step will take the longest time.

Merely increasing the capacity of the cooling apparatus at the cooling station is not sufficient because uncontrolled high rate cooling will result in undesirable chilling of the cast metal at the cooling station, requiring subsequent annealing of the pipe.

After a metal has been poured into a mold, it passes through distinct stages. Initially, the metal is liquid and cools at a rate determined by the thickness of the mold into which it is poured and by the rate at which the mold and the metal within it are being cooled. As the temperature of the poured liquid metal drops, the metal reaches a second, very important stage which may occur either at

75 a single temperature or over a range of temperatures. During this second stage, the metal changes from liquid to solid and in the process liberates its latent heat of fusion. Following this stage, after the metal has given up all of its latent heat of fusion, the metal solidifies, assuming a grain structure which is largely determined by the rate of cooling after the metal has become solid.

Limiting the following part of this explanation to iron for sake of citing a specific example, there exists for iron a rate of cooling which, when exceeded, causes hard, brittle white iron to form. The point at which the rate of cooling becomes critical occurs after the metal has given up its latent heat of fusion and has begun to solidify. In accordance with an important feature of the invention, advantage is taken of the realization that the rate at which the metal is cooled while it is in the liquid state and also while it liberates its latent heat of fusion is not critical and does not significantly affect the quality of the cast metal. Accordingly, in further keeping with the invention, means are provided for cooling the metal at a very high rate while the metal is liquid, including most of the period during which the metal liberates its latent heat of fusion and then changing the rate of cooling just before the metal has liberated all of its latent heat and has begun to solidify at a slower rate which does not cause the metal temperature to drop at a rate at which the metal would begin to acquire the undesirable characteristics of white iron.

More specifically, means are provided for detecting the instant when the cast metal has dropped to the temperature at which it begins to liberate its latent heat of fusion, the time required for the metal to give up all of its latent heat of fusion is predetermined either through calculation or by experiment, and a timing device is set to cause a reduction in the rate of cooling of the metal 35 to occur just before the calculated time has elapsed.

The temperature at which the metal in question solidifies is obviously an important factor in successfully implementing the subject invention. It is thereby important to note that metals and in particular iron compositions do 40 not always solidify at a single temperature. Speaking of iron in particular, the composition may be selected to make the iron solidify at a single, well-defined temperature. An iron having such composition is called eutectic. For sake of simplicity, and again limiting the discussion to iron, it will be assumed at first that the iron which is poured into the mold is eutectic.

Turning now to the metal cooling system and with reference to FIG. 9 at first for a brief general description, coolant is propelled through the poured metal in 50 the mold 32 in station F by means of a spray head located opposite one end of the mold and generally designated by the numeral 210. Located near the other end of the mold 32 is a spectrally selective temperature sensor 220 for monitoring the temperature of the metal in the mold. To control the application of coolant through the spray head 210 in response to the sensor 220 and in particular to reduce the rate of cooling just before the cast metal in the mold has given up all of its latent heat of fusion and has begun to solidify, a cast metal cooling control unit 230 is provided.

The arrangement for propelling coolant through the bore of the pipe 41 within the mold 32 is shown in FIG. 15. Located at one end of the mold 32 is the spray discharge system 210 and an exhaust system for removing steam from within the pipe is shown at the other end thereof.

The spraying system 210 is designed to send intermittent spurts of atomized coolant such as water through the bore of the pipe 41. Upon coming into contact with the hot inner wall of the pipe, the water spurts are turned into steam rings and are extracted from the pipe by the exhaust system. These spurts of water enter the pipe to be cooled through an atomizer nozzle 212. Water is fed to the nozzle 212 from a conduit 214 through a solenoid controlled valve 211. Connected between the valve

211 and the nozzle 212 is an interrupter assembly 213. The function of this assembly is to break up the flow of water through the valve 211 into short spurts of water followed by a quick puff of air. The interrupter assembly 213 includes a main orifice 215 connected between the valve 211 and the atomizer head 212. The orifice 215 opens up into a generally circular casing 216 which houses an interrupter wheel 217 made of a circular molded rubber compound. The wheel 217 has four pockets 218 around its periphery and as the wheel is caused to rotate under the pressure of water admitted through the valve 211, each of the pockets 218 is charged with a small quantity of water which it discharges into the main orifice 215 towards the atomizer nozzle 212. Located between the nozzle 212 and the interrupter wheel 217 and receiving compressed air at a pressure somewhat lower than that of the water is a second orifice 219. Thus as each spurt of water is discharged by the interrupter wheel 217 towards the atomizer head 212, it is followed by a puff of air and is caused to expand into a ring of atomized water as may be seen in FIG. 15.

Upon contacting the hot inner surface of the pipe 41, each atomized spurt of water turns into a ring of steam and is propelled towards the opposite end of the pipe and into the ventilator hood 116. To aid the rapid propagation of steam rings through the interior of the pipe 41, the ventilator hood 116 is connected through an exhaust conduit 117 to an exhaust fan or similar means (not shown) whereby an air current is set up through the bore of the pipe away from the atomizer head 212.

Turning now to the pipe temperature responsive control system for regulating the flow of water through the valve 211, the temperature of the pipe 41 is monitored by a spectrally selective temperature sensor 220 which is directed at the bell end of the pipe and which is shown situated in the ventilator hood 116. Spectrally selective temperature sensors of the type suitable for use as the sensor 220 are widely available commercially. One such instrument is the Spectray 65, made by Leeds Northrup Company, Philadelphia, Pa. The instrument has a sensing element that responds to minute changes in the wave length of the object at which it is directed. In terms of the color response of the human eye, the instrument ranges from light cherry red (1550° F.) through orange, yellow, green, blue, violet, to brilliant bluish white (2950° F.) for molten iron or steel.

For use in automatic control circuits, the instrument produces a signal which is a function of the temperature of the object at which the instrument is directed and this signal is then fed into electronic devices which convert it into a form suitable for actuating various control elements. As seen in FIG. 13, each mold in the cooling stations is individually cooled by a spraying system 210 and is individually monitored for temperature by a spectrally selective temperature sensor 220. In particular temperature sensor 220e and spray system 210e are located at opposite ends of the mold in the cooling station E and temperature sensor 220f and spray system 210f are situated at opposite ends of the mold in the cooling station F.

As stated previously, it is an important object of the invention to cool the cast metal in the molds within the cooling station at a high rate until the metal has released almost all of its latent heat of fusion and then to reduce the rate at which the cast metal is cooled so as to prevent it from being chilled. In carrying out this aspect of the invention, means, indicated on FIG. 9 as the cast metal cooling control 230, are provided for shutting off each control valve 211e and 211f associated with the spray systems 210e and 210f some time after the cast metal in its particular cooling station has begun to liberate its latent heat.

Considering first the cooling system associated with cooling station E (FIG. 13), the solenoid of the control valve 211e is controlled by a control relay CR21e which

5 is turned on so as to open the valve 211e when a pair of molds are indexed into the cooling stations. The remaining portion of the cast metal cooling control system, including a set point temperature controller 231e, a delay 232e and a reset timer 233e are provided for turning off the control relay CR21e so as to shut the valve 211e some time after the cast metal in the cooling station has begun to release its latent heat.

10 The electrical output of the temperature sensor 220e is fed to the set point controller 231e through line 221e. As will be explained with reference to FIG. 14, the set point controller 231e is set to close a relay when the temperature detected by the sensor 220e drops to the temperature at which the cast metal releases its latent heat of fusion. Through a delay 232e, used to prevent premature deenergization of the control relay CR21e, the reset timer 233e is actuated and it in turn shuts off the control relay CR21e a predetermined time after the cast metal in cooling station E began to liberate its latent heat. This time is calculated to occur before the cast metal has released all of its latent heat so as to discontinue high rate cooling of the cast metal before the metal has begun to solidify.

15 To control the cooling of the cast metal in the cooling station F, a similar set of control elements, including a set point controller 231f, a delay 232f, a reset timer 233f, and a control relay CR21f are connected between the temperature sensor 220f and the valve 211f.

20 Reference will now be made to FIG. 14, which shows in detail one of the two metal cooling control systems 230 illustrated in block form in FIG. 13. The structure and operation of a cooling control system 230 will be described principally with reference to FIG. 14, with occasional references to FIG. 13 to indicate the operation of the mold cooling sprays. While the explanation of FIG. 14 is geared to the cooling of a single pipe by a single cooling system, it should be kept in mind that the same sequence of events is taking place, albeit independently, in both of the cast metal cooling control systems of the apparatus, as is apparent from FIG. 13.

25 With reference to FIG. 14, the set point controller 231, which is well known and is manufactured by the West Instrument Corporation of Chicago, Ill., includes a meter pointer 234 and a settable pointer 235. The meter pointer 234 is actuated to travel along a scale 236 of the controller 231 by means of a galvanometer 237 under the influence of the voltage signal generated by the temperature sensor 220 connected to the galvanometer 237. Mounted on the settable pointer 235 30 are a pair of spaced coils 238 which form part of the tank circuit of an oscillator 239 in the set point controller 231. A metal vane 240 is mounted upon the meter pointer 234 and is so placed that when the meter pointer 234 has traveled up the scale to the point where the settable pointer 235 is positioned, the vane 240 is interposed between the coils 238, decoupling them and shutting off oscillation in the oscillator 239 as a result. The output of oscillator 239 is fed to an amplifier 241 whose output is in turn connected to a relay 242 carrying a set of normally closed contacts 242-1. Both the oscillator 239 and the amplifier 241 are energized from a pair of single phase supply lines X1 and X2.

35 So long as the pointers 234 and 235 are at different positions along the scale 236, the oscillator 239 is permitted to operate by virtue of the intercoupling of its coils 238 and, through the amplifier 241, it maintains the relay 242 energized and its contacts 242-1 open. When the meter pointer 234 is brought into alignment with pointer 235 and interposes its vane 240 between the coils 238, the oscillator 239 is shut off, the relay 242 drops out and closes its contacts 242-1. The settable pointer 235 and its coils 238 may be set anywhere along the scale 236 and thus the relay contacts 242-1 may be caused to close at any desired temperature sensed by the sensor 220.

Coolant flows into the pipe interior cooling system through a solenoid operated valve 211, and to appropriately energize the solenoid of the valve 211, a control relay CR21 is provided. Normally open contacts CR213 of the control relay 21 are connected in series with the solenoid of the control valve 211 across the power lines X1, X2, so as to open the valve when the relay is energized. This occurs when the turret 17 indexes a pair of molds from the pouring stations into the cooling stations and triggers a limit switch LS25 which is connected in series with the coil of the control relay CR21 across the power lines X1 and X2. The coil of the control relay CR21 is also connected across the lines X1 and X2 through a second set of contacts CR212 on the relay and through the initially closed contacts 233-1 of the reset timer 233. Through its contacts CR212, the relay CR21 locks in.

With relay CR21 locked in and its contacts CR213 closed, the control valve 211 is opened and cooling of the cast metal in the cooling station through the spray system 210 begins. The presence of the hot molds 32 in the cooling station is also detected by the mold temperature sensors 127 (FIG. 13) causing the valves 126 to open and the mold cooling spray heads 122 to receive and spray coolant on the molds 32. The meter pointer 234, which quickly swept up the scale 236 past the settable pointer 235 (to about 2350° F.) when the sensor 220 initially detected the hot pipe (about 2350° F. for cast iron, see FIG. 12 at d) indexed into the cooling station, now begins to travel down the scale toward the point to which the settable pointer 235 was set.

To initiate the control sequence which will shut off the control valve 211 after release of latent heat by the cast metal, the settable pointer 235 is positioned at the temperature where release of latent heat is expected to occur for the metal being poured. For eutectic iron, this temperature has been determined to be 2150° F. and therefore in FIG. 14 the pointer 235 is shown as being set at 2150° F.

As the cooling cycle continues, the meter pointer 234 indicates the rapidly falling temperature seen by sensor 220 looking at the hot cast metal as heat is rapidly removed by the coolant propelled through the pipe and converted into steam. This rapid extraction of heat energy from the interior surface of the cast metal pipe also reduces the flow of heat from its exterior surface in contact with the mold lining through the mold to its exterior surface. A point is reached where the exterior temperature of the mold drops below the 350° F. set point of the mold exterior temperature controllers 200, (FIG. 11, point a), causing the mold cooling sprays 122 to be shut off. The interior metal cooling units 210 continue to pull the cast pipe temperature down rapidly at a rate which exceeds greatly the cooling rate which the metal can tolerate without chilling after it has solidified. In the temperature diagram of FIG. 12, which is for cast iron, the metal is shown to be cooled at a rate of about 50° F. per second. This high rate temperature drop continues until the metal reaches 2150° F., the point at which the eutectic iron composition begins to release its latent heat.

Once the metal begins to release its latent heat, its temperature remains substantially unchanged until release of latent heat is completed (FIG. 12 at f). Beginning of the release of latent heat by the metal is detected by virtue of the temperature plateau at which the metal remains during the release of latent heat. Thus the settable pointer 235 (FIG. 14) having been set to the temperature of the latent heat release (2150° F.), the vane 240 of the meter pointer 234 comes to rest between the oscillator coils 238 while the cast metal gives up its latent heat. With the vane 240 thus interposed between the coils 238, the oscillator 239, through the amplifier 241 deenergizes the relay 242 and closes its

normally closed contacts 242-1. Closing of contact 242-1 energizes a delay unit 232 causing its contacts 232-1 to close after a suitable delay, typically two seconds. The reason for using the delay 232 is to avoid a false indication of the onset of the release of latent heat when the meter pointer 234 initially sweeps up the dial and momentarily interrupts the coupling between the oscillator coils 238. When the cast metal is being cooled, the meter pointer 234 remains at the temperature of latent heat release for several seconds, and the delay 232 therefore closes its contacts 232-1 approximately two seconds after the onset of release of latent heat.

In keeping with the invention, cooling of the cast metal pipe by the interior cooling spray system 210 continues for a substantial portion of the period during which the metal releases its latent heat but with a provision being made to reduce the rate of cooling before the metal has released all of its latent heat of fusion so as to prevent the continuation of high rate cooling of the metal after the metal has begun to solidify. In keeping with this feature of the invention, means are provided for maintaining the flow of coolant to the internal spray unit 210 for a predetermined time after the cast metal pipe has begun to release its latent heat, this time being calculated to occur before the metal has liberated all of its latent heat. For this purpose, a reset timer 233 is energized from the supply lines X1 and X2 through the delay contacts 232-1. A pair of normally closed contacts 233-1 of the timer 233 are connected in series with the lock-in contacts CR212 of the control relay CR21 so as to cause the relay CR21 to drop out when the timer 233 runs down and its contacts 233-1 open.

After the time required by the metal to release its latent heat under the cooling action of the internal cooling spray unit 210 has been determined either empirically or by calculation, the timer 233 is set to "time out" just before total release of latent heat is expected to occur. This time will, of course, take into account the initial delay introduced by the delay unit 232. Thus, shortly before the cast metal pipe has given up all of its latent heat of fusion, the reset timer 233 times out, its contacts 233-1 open, the relay CR21 drops out, its contacts CR213 open, the control valve 211 is closed and the metal cooling spray is shut off. Very shortly after this event, the flow of heat energy which is now from the cast metal into the molds 32 raises the mold temperature to 350° F. (FIG. 11, point b) causing the mold cooling spray units to be turned on by their temperature controls 200 as the mold temperature sensors 127 detect the rise of the molds above the 350° limit. The mold cooling sprays remain on for the balance of the pipe cooling cycle under the control of the temperature sensors 127 and mold temperature control units 200.

The rate at which heat is removed from the cast pipes within the molds in the cooling station under the action of the mold cooling sprays is governed by the maximum cooling which the cast metal can tolerate after it has solidified without chilling. For cast iron this rate is 15° F. per second. Consequently, the discharge rates of the mold cooling sprays 122 in the cooling stations E and F are set to remove heat at such a rate as to force cooling of the cast pipe at a controlled rate not greater than 15° F. per second (FIG. 12, zones F-G).

To recapitulate, the cast metal pipe in a mold located in the cooling station is first cooled at a high rate by means of the pipe interior cooling system and is then cooled at a lower rate by the mold exterior cooling system associated with the cooling station. Thus the mold cooling system and the pipe interior cooling system may indeed be considered as a single system for cooling the pipe, with the system cooling the metal at a high initial rate (while the pipe interior cooling system is turned on) and at a lower subsequent rate (when the pipe interior cooling system is turned off).

It will be apparent to those skilled in the art that the reduction in the rate of cooling may be achieved by a different control sequence than that described above. For example, where for some reason cooling of the mold per se is not desired, the pipe may be cooled exclusively by the pipe interior cooling system throughout the cooling cycle, and the reduction in the rate at which heat is extracted from the metal may be reduced by merely reducing the rate at which coolant is sprayed into the pipe by the pipe interior cooling system.

(3) The metal composition control system

In the description of the metal cooling system in section B-2 above, it was assumed that the metal used for casting the pipe was eutectic so that the metal had a single well-defined temperature of solidification. Iron which is substantially silicon free is eutectic when it contains 4.3% carbon. If the iron contains less than 4.3% carbon, it is called hypoeutectic, while iron containing more than 4.3% carbon is called hypereutectic. The terms hypoeutectic and hypereutectic signify that portions of the iron composition will begin to freeze at a temperature that is higher than that at which eutectic iron would solidify. In hypoeutectic iron, carbon-free iron will begin to solidify over a range of temperatures higher than the eutectic freeze point, leaving behind liquid iron and carbon. This process continues until the liquid iron is sufficiently enriched in carbon so that its carbon rises to 4.3% at which point the remainder of the liquid solidifies through eutectic solidification. In the case of hypereutectic iron having a carbon content above 4.3%, carbon begins to solidify over a range of temperatures higher than that eutectic freeze point, leaving liquid iron gradually poorer in carbon content until its carbon content drops to 4.3% at which point the remainder of the liquid solidifies through eutectic solidification at the temperature at which the eutectic composition solidifies.

Iron may be made eutectic by adding to it materials other than carbon. For example, a hypoeutectic iron may be made eutectic through the addition of silicon and it has been found that the addition of each percent of silicon to the iron has the same effect in bringing the iron towards the eutectic composition as would the addition of $\frac{1}{3}$ % of carbon. Thus the concept of carbon equivalent (CE) emerged which is commonly used in cast iron metallurgy as a means of comparing irons of unlike composition. Expressed in terms of a formula,

$$CE = \%C + \frac{1}{3}\%Si$$

From a consideration of the above formula, it then appears that a more useful way of referring to a eutectic iron is to state that its carbon equivalent is 4.3% rather than by stating it in terms of carbon content.

Thus it will be seen that a very important result of adding silicon to iron is that by adding the right amount of silicon, a hypoeutectic iron may be made eutectic, bringing its temperature of solidification to a single, well-defined point.

The addition of inoculants, such as silicon, to iron and in particular the late addition of such inoculants to the iron just before it is cast has another important effect upon the solidification process. To appreciate this effect fully, it should be understood that a eutectic composition, including a eutectic iron composition, solidifies through the formation of grains with each grain forming outward from a central nucleus. The number of these nuclei may be increased by the late addition of certain inoculants. Thus, inoculation by increasing the number of nuclei, causes freezing of the eutectic composition to begin at a somewhat higher temperature and at a greater number of points. The effect is twofold: first, the iron that is produced will have a much finer cellular structure than iron that has not been inoculated; second, the inoculated eutectic composition with its higher degree of nucleation is less susceptible to white iron formation. Stated differ-

ently, it has been observed that the higher the degree of nucleation of a eutectic composition, the higher the temperature at which the eutectic composition will freeze and the higher the rate of cooling which the composition will tolerate without undercooling, or in the case of iron, without solidifying as white iron.

According to an important feature of the invention, metal to be poured is given a well-defined freezing temperature, is made less susceptible to undercooling, and is given a finer cellular structure through the late addition of controlled amounts of inoculants, so as to not only improve the cellular structure of the cast metal but also to maximize the rate at which it may be cooled and to give it a well-defined temperature of freezing in order that control equipment which operates by sensing when the metal has dropped to the freezing temperature may operate more precisely.

Before describing the apparatus by which inoculant is added to the metal being poured at the pouring station, the various metal handling units located at the pouring station will be briefly indicated.

Located at the pouring station of the apparatus and generally shown in FIG. 10 are units for maintaining molten metal at a regulated high temperature, for measuring out a suitable amount of metal for pouring into the molds 32, and for inoculating the molten metal so as to improve its composition. The molten metal storing unit generally designated as 250 includes a storage cauldron 82 mounted upon a swing frame 81. Molten metal in the storage cauldron 82 is heated by a heater within the cauldron (not shown) which is fuelled through a fuel mixer 251, from a fuel line 253 and with air through line 255.

To alter the rate at which the cauldron 82 is heated, the flow of air to the mixer 251 is varied by an adjustable air blower 257 under the control of an electronic blower control 259. The temperature of the metal within the cauldron is kept at a desired level by sensing it through a spectrally selective temperature detector 261 and by regulating the flow of air from the air blower 257 so as to diminish the flow of air when the metal temperature sensed by the detector 261 approaches its desired level and by increasing the air flow rate to the mixer 251 when the metal temperature in the cauldron 82 drops too far below the prescribed temperature for the metal. Where the metal is iron, it is desirable to carry out the inoculation of the metal in the pouring boot within the temperature range of 2550° to 2650° F. Consequently, the metal is maintained in the storage cauldron 82 at a temperature of about 2800° F. so as to provide the required margin for heat loss that takes place during the weighing and inoculating steps which follow.

In preparation for the pouring of metal into the molds, a sufficient amount of metal for one pouring is transferred from the storage cauldron 82 to the measuring and pouring bucket or ladle 84 of the measuring and pouring unit 270. The measuring and pouring unit 270 also includes a pouring boot 87 which, in the pouring position, extends into the mouth of the mold 32.

Located directly above the pouring boot 87 of the measuring and pouring unit 270 is an inoculating unit 290 for dropping a suitable amount of inoculant into the metal flowing through the pouring boot 87 while the metal is being poured.

As generally shown in FIG. 10, the inoculating unit includes a storage hopper 291 closed at its bottom by a clam shell 292 which may be opened or closed through a set of links 293 by a hydraulic actuator C6. Located below the clam shell 292 is a weighing hopper 301. Through means to be described, prior to the indexing of each set of molds into the pouring station, an appropriate amount of inoculant is dispensed through the clam shell 292 into the weighing hopper 301 and the amount dropped into the weighing hopper 301 is controlled in accordance with the composition of the iron being stored in the storage cauldron 82.

Commencing a short time after the pouring metal from the measuring bucket 84 to the pouring boot 87 begins, the measured amount of inoculant is discharged from the weighing hopper 301 into the pouring boot 87 so as to mix with the metal flowing through the boot.

Turning now to a detailed consideration of the inoculant applying station 290 and with reference to FIGS. 10 and 16-16b, some time after the indexing of a given pair of molds into the pouring station, metal is transferred from the storage cauldron 82 to the pouring ladle 84 by tilting the storage cauldron upon its swing frame 81. The amount of metal to be poured will, of course, vary with the size and thickness of the pipe to be cast. For a pipe requiring a hundred pounds of molten iron, one hundred pounds of metal will be weighed into the measuring bucket 84. The pouring ladle 84 is supported by a platform 88 of the measuring station 270 and by means which form part of the hydraulic and electrical control system, described in section C, the storage cauldron 82 is automatically tilted back to its rest position when the required amount of metal has been measured into the ladle 84.

During approximately the same period that iron is being measured into the ladle 84, inoculant is measured from the storage hopper 291 into the measuring hopper 301 of the inoculant dispensing station 290 (FIG. 16).

The weighing hopper 301 is hinged upon the weight sensing arms 303 of a weighing scale 305 which swing downward under the added weight of inoculant in the weighing hopper 301. The scale 305 is set by a suitable control 307 to generate a control system signal upon sensing through its arms 303 a given weight of inoculant in the hopper 301.

The manner in which the scale 305 may be preset to generate a control signal in response to a predetermined weight of inoculant in the hopper 301 is shown schematically in FIG. 16. The weight registered by the arms 303 of the scale 305 is indicated by a pointer 313 on a face 309. Also mounted on the face is a set point device 315. When the pointer 313 reaches the set point device 315 (FIG. 16a) a signal is generated by the scale 305 and this signal is fed after amplification to the hydraulic cylinder C6 to close the clam shell 292 when the amount of inoculant for which the scale 305 was set has been discharged into the hopper 301 (FIG. 16b). The position of the set point device 315 is suitably controlled by the control 307.

The amount of inoculant for which the electronic weighing scale 305 is set depends upon the carbon equivalent of the metal in the storage cauldron 82. Thus the carbon equivalent of the metal in the holding cauldron 82 is determined for each load in the holding cauldron 82 by means of a carbon equivalent detector such as the Tec Tip Mark II detector manufactured by the Leeds and Northrup Company in Philadelphia. For example, if the composition of the iron in the storage cauldron 82 is such that it has a carbon equivalent of 4.1%, two "point" of carbon equivalent must be added to the metal by inoculation. Thus, if a pipe weighing 100 pounds is being poured, .6 pound of silicon must be weighed out into the weighing hopper 301 for subsequent release into the hundred pounds of molten metal as the metal runs through the pouring boot 87 into the spinning mold 32, .6 pound of silicon being equivalent in effect to .2 pound of carbon.

A short time after the molds 32 have been indexed into the pouring station, the weighing unit 270 is traversed toward the turret 17 so as to bring the pouring boot in position under the weighing hopper 301 and next to the mold 32 (FIG. 16a). Next, the measuring bucket 84 is automatically caused to tilt so as to discharge its contents into the pouring boot 87. The tilting of the bucket 84 in turn causes the hydraulic cylinder C7 to open the gate 311 of the measuring hopper 301 so as to discharge the contents of the hopper 301 into the metal as it flows through the pouring boot 87 into the mold 32 (FIG. 16b).

C. HYDRAULIC AND ELECTRICAL CONTROL SYSTEMS FOR AUTOMATIC OPERATION OF THE CASTING MACHINE

(1) In general

As was explained in Section A in connection with the operation of the different stations of the machine, it is an important feature of the casting machine that the operations at its four stations, namely lining of a mold at the lining station, the charging of a mold and the lining of a bell mandrel at the pouring station, the rapid cooling of a pipe in the mold in the cooling station, and the extraction of the finished pipe from the mold in the extracting station, are all carried out concurrently. It is the function of the hydraulic and electrical control systems to initiate the various operations at the several stations each time the turret is rotated 90°.

It is a further feature of the apparatus accomplished by the hydraulic and electrical control systems that each series of operations carried out at the several stations around the turret is completely automatic. Further, the turret cannot rotate until every operation has been completed at the several stations and similarly, cooperating elements at the several stations are so interlocked that if in a multi-step operation at a station, a particular step is not performed due to failure of a component, the next step of that series will not take place and the entire apparatus will stop.

All operations in the machine are automated by detecting through limit switches, temperature sensors, or optical sensors, the completion of a step and by triggering the hydraulic cylinder for initiating the next step in response to detection of the proper signal by the sensor. In FIGS. 17-17b are shown the several elements of the casting machine, together with the sensors for detecting the proper positioning of the apparatus. FIGS. 17-17b also show the hydraulic cylinders for actuating the several parts of the machine and the solenoid operated valves for applying fluid under pressure to the cylinders.

The electrical control system of the apparatus appears in FIGS. 18-18d which form a single schematic drawing with each of the five sheets being joined at its top to the bottom of the preceding sheet. The electrical system diagram shows the manner in which the various detecting devices such as limit switches and temperature detectors are connected to actuate through control relays the solenoid operated valves which control the hydraulic cylinders shown in the hydraulic system diagram.

In the following sections, the hydraulic and the electrical control systems will be described for each major function performed at the several stations of the casting machine. In following this description, it should be kept in mind that the different series of operations which take place at several stations occur concurrently, beginning with the instant when a set of molds is indexed into the stations by the mold carrying turret.

(2) Starting the auxiliary apparatus

To provide fluid under pressure to the fluid operated cylinders of FIGS. 17-17b, a hydraulic pressure system is provided. As shown in FIG. 17, fluid drawn from a reservoir 352 is brought up to the desired pressure determined by a relief valves 354 and 356 by a pair of pumps 358 and 360. The pumps 358 and 360 are powered by an electric pump motor MTR1 (FIG. 18) and send fluid under pressure through the supply line 362 to operate the several hydraulic cylinders C1-C19 through their associated solenoid operated valves SV1-SV14. A return path for the fluid from the valves is provided by a return line 364 which returns the fluid to the reservoir 352 through a filter 366.

Cooling water for the mold cooling system and for the internal metal cooling system is supplied under pressure by a cooling water pump (not shown) powered by a pump motor MTR2.

Cooling air is supplied to the spray head of the internal cooling unit by the cooling air blower motor MTR3 and power to turn the turret 17 is provided by the turret index drive motor MTR4 (97 in FIG. 1).

Each of the motors MTR1, MTR2, MTR3, and MTR4 is powered from a three phase line L1, L2, L3, through a set of disconnect switches SW1-SW4. Single phase power for starting the motors and for other electrical units is derived from lines L1 and L2 through contacts of the disconnect switch SW1 and through the isolating transformer 368. Thus, lines X1 and X2, connected to opposite ends of the secondary winding 370 of transformer 368, carry single phase power to the entire electrical system of FIGS. 18-18d.

Each of the three main motors MTR1-MTR3 is started by means of a standard starting circuit which for the motor MTR1 includes the relay MR1 whose coil is connected between the lines X1 and X2 through the start switch 372 and the stop switch 374. The three power lines of the motor MTR1 are connected to the lines L1, L2, and L3 through the three contacts MR11 of the starting relay MR1. To start the motor MTR1, the start switch 372 is closed, energizing the starting relay MR1 and closing its switch contacts MR11. The starting relay immediately locks in through its lock-in contact MR12 which shunts the start switch 372 so that even after it is released, the relay of the starter MR1 is energized. To stop the motor MTR1, the stop switch 374 is opened so as to interrupt flow of current through the lock-in contact MR12 and the coil of the relay MR1.

Similar starters MR2 and MR3, are provided for the motors MTR2 and MTR3 respectively.

Prior to the automatic operation of the pipe casting machine, it is desirable to check out its individual stations. Accordingly, before automatic operation is begun, the motors MTR1, MTR2, and MTR3 are started up by closing of their respective start switches 372, 376, and 378. As a result, the hydraulic pumps bring the line pressure up to the presetting of the relief valves 354 and 356, the cooling water pumps circulate water at the preset pressure of their system (not shown), and cooling air is made available at the cooling station at the desired pressure.

To permit manual check out of the subunits of the machine, the starting circuit at each of the subunits (to be described more fully in connection with each such unit) may be set into either an automatic or a manual mode of operation by means of a multi-deck Manual-Automatic switch CS1 (FIG. 18). The switch CS1 has eight sets of contacts CS11-CS18, each in the starting circuit of a different subunit of the machine. With the switch CS1 in manual position, each of its contacts CS11-CS18 is open, and in each starting circuit the respective contact of switch CS1 serves to disable the automatic starting circuit so as to permit manual starting through the pressing of its manual start switch.

After each of the subunits have been checked out manually, the Manual-Automatic switch is CS1 is changed to automatic operation so as to close each of its contacts CS11 through CS18 in the various starting circuits of the machine.

To provide automatic indexing of molds in the turret from station to station, the starting circuit of the turret index drive motor MTR4 includes in addition to standard starting circuit such as those associated with the motors MTR1-MTR3, an auxiliary starting relay CR1 whose coil is connected in series with the deck CS11 of switch CS1 and whose contacts CR11 serve to complete a connection from line X1 to the coil of the starting relay MR4. To prevent damage to any of the subunits which must periodically extend into the body of the turret 17, each such subunit contains a limit switch which is closed only when the subunit is fully retracted. As seen in FIG. 18, seven limit switches LS1-LS7 associated with seven subunits are connected in series with the contact CR11. An additional pair of switches IT2e and IT2f are connected

in series with the limit switches LS1-LS7 and are operated by the internal temperature controllers 230e and 230f respectively (FIG. 18d). The switches IT2e and IT2f are closed only when both of the pipes in the cooling stations have cooled to 1600° F., this being the criterion for judging the completion of the cooling operation in the cooling system which must be allowed to take place before a pipe is indexed out of the cooling station. With the Manual-Automatic selector switch CS1 in the automatic position, when all of the limit switches LS1 through LS7 and the switches IT2a and IT2f of the temperature controller are closed, indicating that all machine members have been withdrawn and that the pipe in the cooling station has cooled sufficiently, a circuit is established between the lines X1 and X2 through the switches just named to energize the starter relay CR1 of the turret index drive motor MTR4. As a result, the starter relay CR1 pulls in its contact CR11 which in turn energizes the coil of starter relay MR4 to close its contact MR41 so as to apply power from the lines L1, L2, and L3 to the turret index drive motor MTR4. Thus energized, motor MTR4 indexes the turret 90° at which time the turret opens a limit switch LS1A connected in series with the limit switches LS1-LS7 so as to stop the turret in that position.

During the motion of the turret 17, index stops mounted on the turret 17 trip a series of limit switches so as to initiate the operation of the several subunits. The subunits and the limit switches for initiating their operation 30 are the following: (a) coating cycle, limit switch LS9 (FIG. 17), (b) pouring unit, limit switch LS12 (FIG. 17a), (c) bell mandrel forming and indexing, limit switch LS18 (FIG. 17b), (d) internal water cooling spray, limit switches LS25-1 and LS25-2 (FIG. 17b), (e) pipe extracting unit, limit switch LS27 (FIG. 17b).

The hydraulic and electric controls for automatically sequencing the operation of the individual subunits in response to the tripping of their associated limit switches will now be described.

(3) The coating station

As described earlier in connection with FIG. 1-3 and as again shown in FIG. 17, the mold coating station includes a motor MTR5 having a spin disc 42 for spinning the molds 32 in the mold coating station. The motor MTR5 is mounted on a carriage 44 which rides upon a rail 46. After the turret 17 has indexed a pair of molds 32 into the mold coating station, the carriage 44 is advanced on its track 46 to bring the motor spin disc 42 into engagement with the spin bands 90 on the molds 32.

After the molds have been brought up to suitable spinning speed, a pair of spray nozzle assemblies 45 mounted upon a carriage 70 are advanced into the molds and while the spray nozzle assemblies 45 are within the molds, 55 a mixture of refractory material and binder is sprayed through them against the spinning inner surface of the molds in the mold cooling station.

To traverse the mold coating spin drive carriage 44 towards and away from the turret 17, a hydraulic cylinder 60 C1 having a piston rod 392 connected to the carriage 44 is provided. Connected between the supply and return lines 362 and 364 of the hydraulic system and the hydraulic valve C1 is a solenoid actuated double acting center neutral valve SV1. The valve has two solenoids SV1A and SV1B for controlling the position of its spool 394. With the coil SV1A energized, the spool is drawn to its upper position and fluid passes from the supply line 362 through the supply connecting line 396, the valve SV1 and valve outlet line 398 to the closed end of the cylinder C1, with the return path of fluid from the rod end of the cylinder to the return line 364 being through the valve outlet line 400, the upper chamber of the valve SV1 and the return connecting line 402.

Conversely, when the solenoid coil SV1B is energized, the spool 394 is drawn downward and fluid under pres-

sure is fed from the supply line 362 to the rod end of the cylinder C1 through the connecting line 404 into and through the top portion of the chamber in the valve SV1 and through the valve outlet line 400. The return path for the fluid from the head end of the cylinder C1 to the return line 364 is through the line 398, through the bottom valve chamber, and finally through the line 402.

When neither of the coils SV1A or SV1B are energized, the spool 394 is positioned intermediate its end positions and the cylinder C1 is locked at the position in which it was when the spool was released into its unenergized central position.

The double acting solenoid operated valve of the type described for the valve SV1 is used through the system and although shown only in block form for the remaining double acting valves, it will be understood that unless otherwise indicated, all of these valves operate in the same manner as the valve SV1, namely that with its top coil actuated, the valve sends pressurized fluid through its bottom outlet line and receives fluid through its top line and that when the bottom coil is energized, pressurized fluid is sent through the top outlet line of the valve and is returned through its bottom outlet line.

To control the energization of the coils SV1A and SV1B, the electrical control system (FIG. 18a) includes a pair of control relays CR2 and CR3 with the relay CR2 having a normally open contact CR21 connected in series with the coil SV1A and relay CR3 having a normally open contact CR32 in series with the coil SV1B. The relay CR2 has a second contact CR22 for locking in the coil of the relay CR2. Associated with the relay CR2 is a starting circuit for energizing and locking in that relay. This starting circuit includes the start switch 407 and the stop switch 406 connected in series with each other and with one terminal of the coil of the relay CR2 whose other terminal connects to the line X2. Connected in parallel with the start switch 407 is the limit switch LS9 connected in series with the contacts CS12 of the Manual-Automatic control switch CS1. The stop switch 406 is connected to the line X1 through the normally closed contacts CR31 of the relay CR3.

As the turret 17 indexes a pair of molds into the mold coating station, it trips the limit switch LS9 (FIG. 17) and through contacts CR31, the stop switch 406, limit switch LS9, and switch contacts CS12 the coil of relay CR2 is energized, and its contacts CR21 and CR22 both close. By closing of the contacts CR22, the relay CR2 is locked in. Through the contacts CR21, now closed, the valve solenoid coil SV1A is energized, admitting fluid under pressure through the bottom outlet of the valve SV1 to the closed end of the cylinder C1. Thus actuated the cylinder traverses the mold coating spin drive carriage 44 towards the turret 17.

The travel of the carriage 44 towards the turret continues until the spin drive discs 42 engage the spin band 90 of the molds 32. This condition is sensed by the limit switch LS8 which is triggered by the forward camming surface 410 of the carriage of FIG. 17. With the mold coating spin drive thus in position, the motor MTR5 is then brought up to speed under the control of the automatic acceleration and deceleration unit 412 by a motor generator set 414. When the limit switch LS8 is closed by the camming surface 410, indicating that the motor MTR5 is in driving connection through the spin disc 42 with the molds 32, the limit switch LS8 connects a timer RT1 across the lines X1 and X2. One output 416 of the timer RT1 is connected to the automatic acceleration and deceleration unit 412 and causes it to commence operations bringing the motor MTR5 up to speed gradually.

Once the molds have been brought up to the proper spinning rate by the motor MTR5, the next step is to traverse the mold coating car towards the turret so as to carry the spraying units 45 into the molds that are to be coated. The mold coating car 70 is moved into and out of

the turret 17 by hydraulic cylinder C4 (FIG. 17) which is controlled by the solenoid operated control valve SV2. Control over the energization of the solenoids SV2A and SV2B of the valve SV2 is accomplished by the relays CR4 and CR5 (FIG. 18a).

The winding of relay CR4 is connected between the lines X1 and X2 for manual starting through the start switch 420 and the normally closed contact CR51 of the relay CR5. For automatic energization of the relay CR4 upon full speed spinning of the molds in the mold coating station, its winding is connected across the lines X1 and X2 through the contacts CS13 of the Manual-Automatic switch CS1 and through the normally open contacts RPM12 of the RPM device RPM1. This device is connected to the motor MTR5 and closes its contacts when the speed of rotation of the motor is sufficient to revolve the molds at the rate required for the coating operation. With the motor MTR5 up to operating speed, contact RPM12 close and the relay CR4 is energized. Through its contacts CR42, the relay locks in. Both the RPM device RPM1 and the relay CR4 carry an additional pair of normally open contacts RPM11 and CR41 respectively which are connected in series with each other between one terminal of the solenoid SV2A and the line X1. The other terminal of the solenoid SV2A is connected to line X2 so that with the molds up to spinning speed and the relay CR4 closed, the solenoid SV2A is connected across the lines X1 and X2 through the switch contacts RPM11 and CR41 and is energized. As a result, the control valve SV2 applies fluid under pressure from supply line 362 to the closed end of the hydraulic valve C4 causing the mold coating car 70 to be traversed towards the turret 17.

A sand and binder metering unit 422 regulates the opening of hopper 50 into the spray units 45. Through a pair of solenoid actuated valves 423 the metering unit 422 also regulates the flow of binder from the binder tank 425 to the spray nozzle assemblies 45 through binder supply lines 63. The sand and binder metering unit is controlled by a timer RT2 which is started at the commencement of the mold coating car into the turret 17. For this purpose, the timer RT2 is connected across the lines X1 and X2 through a normally open set of contacts CR43 of the relay CR4. Thus as the relay CR4 is energized due to closure of contacts RPM12 so as to cause inward travel of the mold coating car 70, its normally open contacts CR43 cause the timer to become energized and its normally open contacts RT21 to close thus connecting the sand and binder metering unit 422 across the power lines X1, X2 through lines 426 and 428.

When the mold coating car has completed its travel towards the turret 17 and the spraying units 45 have been completely traversed into the molds 32 at the coating station of the turret 17, the mold coating car reverses its direction of travel and retracts the spraying units 45 from the molds. Retraction of the mold coating car away from the turret is initiated by a limit switch LS1a which is closed by a stop 429 on the mold coating car 70 at the instant when the mold coating car has reached the limit of its travel towards the turret 17.

Closing of the limit switch LS1a completes a circuit connecting the coil of relay CR5 across lines X1 and X2. With the relay CR5 energized, its normally open contacts CR53 complete a circuit connecting solenoid SV2B across lines X1 and X2. At the same time, through its normally closed contacts CR51, the relay CR5 deenergizes the solenoid SV2A. With the control valve solenoid SV2B energized, and the solenoid SV2A deenergized, the control valve SV2 reverses the flow of fluid through the hydraulic cylinder C4 applying fluid under pressure to the rod end of the cylinder thereby causing the cylinder C4 to retract the carriage 70, away from the turret 17. As the carriage is thus retracted, the limit switch LS1a opens. However, the relay CR5 remains energized through its normally open contacts CR54 which establish an alternate connection from the coil of the relay CR5 through the

limit switch LS1b to the line X1. Limit switch LS1b is held closed during all positions of the mold coating car 70 except its fully retracted position by the switch operating arm 430 mounted upon the mold coating car 70. When the mold coating car 70 completes its rearward travel away from the turret 17, the limit switch LS1b opens, interrupting the circuit of the relay CR5 through the contacts CR54 and as a result the relay opens its normally open contacts CR53 and deenergizes the solenoid SV2B thus cutting off further pressurized fluid from the rod end of the cylinder C4.

During the period that the mold coating car 70 carried the spray nozzle assemblies into the molds in the mold coating station, a timer RT2 was maintained energized through the normally open contacts CR43 of the relay CR4. In connection with this, it was indicated that when the mold coating car 70 reaches the limit of its travel, the relay CR4 is deenergized due to the opening of the normally closed contacts CR51 of the relay CR5. Because the timer RT2 is maintained energized during the inward travel of the mold coating car 70 by the normally open contacts CR43 of the relay CR4, the circuit which was theretofore maintained to the timer RT2 through the relay contacts CR43 must be replaced and this is accomplished through the normally open contact CR52 of the relay CR5 so that as the mold coating car 70 begins its rearward travel out of the turret 17, the timer RT2 is maintained energized through the contacts CR52.

With the mold coating car 70 fully retracted, relay CR5 is deenergized due to the opening of limit switch LS1b and hence the timer RT2 is deenergized and after suitable delay opens its normally open contacts RT21 so as to cut off the power from the Sand and Binder Metering Unit 422.

A preset time after the mold coating car has been fully retracted, the mold coating spin drive is disengaged from the molds in the coating station by withdrawal of the spin drive carriage 44. Disengagement of the spin drive from the molds is carried out by the reset timer RT1 which times out a short time after the mold coating car is expected to reach its rest position. At this instant the normally open contacts RT11 of the reset timer RT1 close, so as to energize the coil of relay CR3. Through its normally closed contacts CR31, the relay CR3 interrupts the circuit from line X1 through stop switch 406, limit switch LS9, and control switch contact CS12 to the winding of relay CR2. As a result, contacts CR21 of the relay CR2 open and interrupt power to the solenoid SV1A of the control valve SV1. At the same time, the normally open contacts CR32 of the relay close and apply power to the solenoid SV1B of the control valve SV1. Thus, due to the closing of contacts RT11 of the timer RT1 after return of the mold coating car carriage 70 to its rest position, the solenoid SV1B of the control valve SV1 is energized and the solenoid SV1A of that valve is deenergized.

In accordance with the operation of the control valve as described earlier, deenergization of the solenoid SV1A and energization of solenoid SV1B causes the spool 394 of the valve to drop to its lower position causing pressurized fluid to be applied to the rod end of the hydraulic cylinder C1, and the cylinder C1 to withdraw the mold coating spin drive carriage 44, thus disengaging the spin drive from the molds in the turret.

Once the mold coating spin drive assembly is disengaged, the motor MTR5 is cut off by the opening of limit switch LS8 which interrupts the circuit to the reset timer RT1. This marks the end of the operation of the mold coating subunit.

(4) The pouring station

(a) Measuring into the pouring ladle.—The first step performed by the pouring subunit is that of transferring sufficient molten metal from the holding cauldron 82 to the pouring ladle 84 for pouring a pipe. As seen in FIG. 17a,

the storage cauldron 82 is supported upon a swing frame 81 resting upon a platform 83. Located next to the lip of the storage cauldron 82 is the pouring ladle or bucket 84 which is pivotably supported on a swing frame 85 mounted upon the weighing platform 88 of the measuring and pouring unit 270.

To transfer metal from the storage cauldron 82 to the measuring ladle 84, a hydraulic cylinder C5 is connected to the cauldron 82 so as to rock the cauldron forward upon its frame 81 when fluid under pressure is sent to the closed end of the cylinder.

To detect the rest position and the pouring position of the cauldron 82, it is provided with a camming surface 440 associated with a limit switch LS11 located underneath the cauldron 82 and closed when the cauldron is at its rest position, and with a limit switch LS30 located at the rear of the cauldron and closed by the camming surface 440 when the cauldron has been fully raised by the cylinder C5.

The pouring ladle 84 has two lateral positions. In its first position, it is situated next to the storage cauldron so as to receive a charge of metal when the cauldron is tilted. In this position the measuring platform 88 closes a limit switch LS10 to indicate that it is safe to carry out the pouring operation. In its second position, the pouring ladle 84 and its associated pouring boot 87 are situated near the turret 17 so as to bring the throat of the pouring boot 87 into the mouth of the mold 32 in the turret 17. To bring the pouring ladle 84 and the pouring boot 87 into this pouring position, the entire measuring and pouring unit 89 is traversed away from the storage cauldron 82 toward the turret 17 by means of a hydraulic cylinder C9.

The temperature of metal in the storage cauldron 82 is monitored continuously by a spectrally selective temperature sensor TS1. Contacts TS11 of this temperature sensor are interlocked with the cauldron tilt control circuit (FIG. 18b) so as to prevent tilting of the storage cauldron 82 unless the metal within it is above a prescribed temperature.

Tilting of the storage cauldron 82 by the hydraulic cylinder C5 is controlled principally by the control valve SV3. With the solenoid SV3A energized, fluid under pressure from the supply line 362 is routed to the closed end of the cylinder C5 through the control valve SV3, and through the valve bypass line 442. Connected in parallel with the bypass line 442 is a control valve SV4 which when opened functions to supply an additional path for fluid from the valve SV3 to the closed end of cylinder C5. The control valve SV4 is spring biased into its open position, and is closed by energization of its solenoid SV4A.

To tilt the cauldron 82 rapidly, solenoid SV3A is energized while SV4A is left unenergized, so as to provide a second flow path in parallel with bypass 442 for pressurized fluid from the control valve SV3 to the cylinder C5. Then, in order to diminish the rate of tilting of the cauldron 82 by the cylinder C5, the solenoid SV4A is energized permitting the valve SV4 to be closed so as to reduce the path for the pressurized fluid to the cylinder C5.

When it is desired to return the cauldron 82 to its rest position, solenoid SV3A is deenergized and the solenoid SV3B is energized instead, causing pressurized fluid to be channeled to the rod end of the cylinder C5.

Energization of the solenoid SV3A is controlled through relay CR6 (FIG. 18b). The solenoid SV3A is connected across power lines X1 and X2 through normally open contact CR61 of the control relay CR6 and through contacts TS11 of the temperature sensor TS1. Thus, solenoid SV3A becomes energized only when the metal temperature in the storage cauldron 82 is sufficiently high and when the control relay CR6 has been energized. The other winding of control relay CR6 is connected across lines X1 and X2 through contacts CS14 of the Manual-Automatic switch CS1, limit switch LS12, normally closed contacts

CR91 of control relay CR9, and through limit switch LS10 and LS11. Consequently, if the limit switch LS10 is closed, indicating that the pouring ladle 84 has been brought next to the storage cauldron 82 and if the limit switch 11 is closed indicating that the storage cauldron 82 is in its lowered position, a circuit is established through the limit switch LS12 as the molds are indexed into the pouring station to energize the relay CR6 and the solenoid SV3A.

The control relay CR6 locks in over its contacts CR62 and remains energized. Solenoid SV3A thus remains energized through contacts CR61 of the control relay CR6 and commences to apply fluid under pressure to the closed end of hydraulic cylinder C5 thus raising the storage cauldron 82.

Initially, the control valve SV4 which controls the rate at which the storage cauldron 82 is being tilted is not energized. The control valve SV4 is spring biased into its open position and is closed only when its solenoid SV4A is energized. Consequently, initially fluid under pressure flows through both the bypass 442 and through the control valve SV4 so that the storage cauldron is raised at a high rate.

The rate at which the storage cauldron 82 is raised by the hydraulic cylinder C5 is reduced as the level of liquid in the pouring ladle 84 approaches its desired level. To detect the level of liquid in the ladle 84, a pair of optical sensors OS1 and OS2 are mounted at one side of the ladle 84 which is provided with a pair of optically transparent windows 444 and 446 in alignment with the sensors OS1 and OS2. The first sensor and its associated opening 444 are so located as to detect the level of liquid in the ladle 84 in time to lower the pouring rate from the cauldron 82 without overshooting the final level that the metal is to reach in the ladle 84.

Each of the optical sensors OS1 and OS2 has a relay (FIG. 18b) whose contacts close when the sensor detects metal at its associated ladle opening. Contacts OS1A of the sensor OS1 are connected in series with a control relay CR7 and with the normally closed contacts CR81 of an additional control relay CR8 in a circuit connected across the lines X1 and X2. The normally open contacts CR71 of the control relay CR7 are connected in series with the solenoid SV4A of the control valve SV4 in a circuit also connected across the power lines X1 and X2. Consequently, at the instant when the level of liquid in the ladle 84 reaches the window 444 and is detected by the sensor OS1, sensor contact OS1A closes and energizes control relay CR7 whose normally open contact CR71 closes and completes the circuit which connects solenoid SV4A across the lines X1 and X2. Energization of solenoid SV4A closes the control valve SV4 and reduces the flow path to the closed end of the hydraulic cylinder C5 thus reducing the rate at which the cauldron 82 is tilted upward.

Just before the cauldron 82 is to be returned to its rest position, the control valve SV4 is opened in response to a signal from the second optical sensor OS2. For this purpose, the normally open contacts OS2A which close when the level of metal reaches the second window 446, are connected in series with the coil of control relay CR8 in a circuit connected across lines X1 and X2 so that when the liquid level rises to the second window 446, the control relay CR8 is energized. Its normally closed contacts CR81, connected in series with the coil of control relay CR7, open and the control relay CR7 drops out, causing solenoid SV4A to be deenergized and the valve SV4 to be biased to its normally open condition.

Almost instantaneously, the zero reset contacts SC1 of an electronic weighing scale 89 associated with the measuring and pouring units 270 are responsive to the amount of weight on the measuring platform 88 close, indicating that the weight of metal for which the scale 89 was preset has been poured into the pouring ladle 84.

With the limit switch LS30 closed by the cam 440, indicating that the storage cauldron is tilted, contact SC1

of the electronic weighing scale connects the coil of control relay CR9 across lines X1 and X2 causing it to close its normally open contacts CR92 and to open its normally closed contacts CR91. Opening of the contacts CR91 causes the control relay CR6 to drop out and through its contacts CR61 to interrupt flow of current through the solenoid SV3A. At the same time, closing of the contacts CR92 completes a circuit connecting the solenoid SV3B across lines X1 and X2 thus applying pressurized fluid to the rod end of cylinder C5 so as to return the cauldron 82 toward its rest position. With the control valve SV4 open, this operation occurs quite quickly.

There has thus far been described the first step in the operation of the pouring subunit during which molten metal is quickly poured from the storage cauldron 82 to the pouring ladle 84. Before the next step in the operation of the pouring subunit can occur, namely that of traversing the measuring and pouring unit 270 towards the turret 17, a pair of lined bell forming mandrels must be inserted into the bell ends of the mandrels in the pouring station. This operation is performed on the molds located by the turret in the pouring station by a bell mandrel lining unit which is located approximately in alignment with the pouring subunit but at the opposite end of the turret 17.

(b) Inserting the bell mandrels into the pipe molds.— With reference to FIG. 17b, two pairs of bell end cores or mandrels 182 and 184 are mounted on a rotatable turret plate 166. The turret plate 166 is carried by a shaft 185 actuated for lateral movement by a hydraulic cylinder C12 so that as fluid is applied to the closed end of the hydraulic cylinder C12, the rod of the cylinder advances the turret plate 186 with the mandrels on it towards the turret 17. Connection of the hydraulic supply and return lines 362 and 364 to the hydraulic cylinder C12 is through the control valve SV8 which connects the supply line 362 to the closed end of the cylinder C12 when its solenoid SV8A is energized. With its solenoid SV8B energized, the control valve SV8 connects the supply line 362 to the rod end of the cylinder C12 for retracting the turret plate 186.

Mounted below the turret 17 is the lining cabinet 190 described earlier in connection with FIGS. 1 and 7. The lining cabinet includes a pair of split molds or forms 191 which when closed are adapted to receive the two bottom mandrels 184 on the turret plate 186. The split molds 191 are controlled by a pair of hydraulic cylinders C14 and C15 with top mold being moved by the cylinder C14 and the bottom mold by the cylinder C15. Both hydraulic cylinders are under the control of a single control valve SV9 which connects the closed ends of the cylinders C14 and C15 to the hydraulic supply line 362 so as to close the forms when the solenoid SV9A of the control valve is energized. Conversely, to open the molds 191, solenoid SV9B of the control valve SV9 is actuated which causes the hydraulic supply line 362 to be connected to the rod ends of the cylinders C14 and C15.

In the rear of the split molds 191 is an opening adapted to receive an extruder 195 for injecting a lining compound into the molds around the cores 184. The extruder 195 is moved towards or away from the split molds 190 in alignment with the opening therein by a hydraulic cylinder C16 actuated by a control valve SV10. Control valve SV10 has only a single solenoid SV10A. With the solenoid SV10A deenergized, the spindle of the control valve is biased into its rest position in which the valve connects the hydraulic supply line 362 to the rod end of the cylinder C16 so as to retract the extruder 195 from the molds 191. With the solenoid SV10A energized, the spindle of the valve shafts and a path is established through the valve from the supply line 362 to the closed end of the cylinder C16 causing the cylinder to traverse the extruder 195 into its opening in the molds 191.

In order to initiate the several steps performed by the lining subunit, a first limit switch LS13 indicates when

the turret plate 186 has been extended fully so as to place the cores 182 and 184 in engagement with the molds in the turret and in the lining cabinet respectively. A second limit switch LS19 indicates when the mold halves 191 have been fully closed, and a third limit switch LS20 indicates when these halves have been fully opened.

Turning now to the operation of the mandrel lining subunit, the step which immediately follows the previously described step of the pouring subunit will now be described.

As the turret indexes the molds into the pouring station and hence in alignment with the bell mandrels 182, a limit switch LS18 is triggered by a stop 448. The limit switch LS18 is connected in series with the coil of control relay CR14 (FIG. 18c) through contacts CS16 of the Manual-Automatic control switch CS1 in a circuit which connects the coil across the power lines X1 and X2. With the limit switch LS18 closed, the control relay CR14 is energized and is locked in through its normally open contacts CR141 which by-pass the limit switch LS18. Through its second normally open contacts CR142, the control relay CR14 completes a circuit connecting the solenoid SV8A across lines X1 and X2 causing the control valve SV8 to apply pressurized fluid to the closed end of hydraulic cylinder C12 so as to traverse the turret plate 186 towards the turret 17 and the lining cabinet 190.

As the cores 182 and 184 are being advanced towards the turret and the lining cabinet 190, a command signal is also issued to close the molds 191 of lining cabinet 190 in readiness to receive the bottom pair of cores 184. This is accomplished by a third set of normally open contacts CR143 on the control relay CR14 which connect the winding of further control relay CR15 across the lines X1 and X2 through the normally closed contacts 182 of an unenergized control relay CR18. The energized control relay CR15 closes its normally open contacts CR151 and through them connects the solenoid SV9A across the lines X1 and X2. In response the control valve SV9 applies fluid under pressure to the closed ends of hydraulic cylinders C14 and C15 thereby advancing the two halves of the lining molds 191 towards each other until they become closed.

Upon closing of the two halves of the lining molds 191, the extruder 195 is advanced into its position at the rear of the lining molds 191 and a timer RT4 is started so as to retract the extruder 195 and to open the lining molds 191 when the lining on the cores in the cabinet 191 has cured.

To advance the extruder 195 in response to the closure of the lining molds 191, a limit switch LS19 is connected in series with the winding of a control relay CR16. The limit switch LS19 closes its normally open contacts when the lining molds 191 are fully closed so that closure of the cabinet 190 is signaled by completion of a circuit connecting the coil of control relay CR16 across the lines X1 and X2 so as to energize the relay. Through its normally open contacts CR162, the control relay CR16 closes a circuit which connects the solenoid SV10A across the lines X1 and X2 through the normally closed contacts of the timer RT41. Since the timer RT4 maintains its contacts RT41 closed until the timer times out, the solenoid SV10A is energized and opens the valve SV10 so as to apply power to the closed end of control cylinder C16 thus advancing the extruder 195 into its position at the rear of the lining cabinet 190.

The timer RT4 is also provided with a second set of contacts RT42 which are normally open and which close when the timer times out. Contacts RT42 are in series with a circuit which in turn applies fluid under pressure to the rod ends of the hydraulic cylinders C14 and C15 so as to separate the lining molds 191 of the lining cabinet 190. At the same time, the timer RT4 also causes the extruder 195 to be retracted through operation of its normally closed contacts RT41 which open when the timer RT4 times out. With the contacts RT41 open, the circuit

which connected the solenoid SV10A across lines X1 and X2 is interrupted and the solenoid operated valve SV10 is spring returned to its normal position in which fluid under pressure is applied to the rod end of cylinder C16.

5 The timer RT4 is set to close its normally open contacts RT42 and to open its normally closed contacts RT41 a period of time after the timer is initially energized, this time being calculated to correspond to the curing time of the linings on the mandrels in the lining cabinet 190. To initiate the timing operation of the timer RT4 it is connected across lines X1 and X2 through the normally open contacts CR161 of the control relay CR16 which as will be recalled is energized by the closure of the limit switch LS19 at the instant when the molds of the lining cabinet 190 are closed.

10 It is well to note at this point that as operations progress in the pouring subunit and the mandrel lining subunit, closure of the lining cabinet molds 191 follows very closely in time the transfer of metal from the storage 15 cauldron 82 to the pouring ladle 84. Since the progress of operations in the pouring subunit was left at the point where metal was being transferred from the storage cauldron 82 to the pouring ladle 84, description of the apparatus will now be resumed with the next operation to 20 take place in the pouring subunit with the comment that as this next operation takes place, the mandrels 184 are being cured in the lining cabinet 190 and the timer RT4 is running down towards the point where it will time out at which time the description will return to the mandrel lining subunit.

25 (c) Spinning of the pipe molds in the pouring station.—With the mandrels 182 inserted in the pipe molds 32 and the mandrels 184 in the mandrel lining cabinet 190, the pipe molds 32 together with the mandrels inserted in their bell ends are brought up to speed by a spin drive unit located underneath the turret 17. As best seen in FIG. 17a and as previously described in connection with FIGS. 1 and 2, the drive unit is mounted upon a vertically movable platform 98. With the platform 98 30 fully raised, the spin drive unit engages a spin band 90 on the pipe mold 32. Driving the spinner 111 through a belt 107 and a shaft 103 is a main drive motor which in FIG. 1 is identified by the numeral 97 but which in the electrical system diagram of FIG. 18c is labeled as 35 MTR6.

40 The metal pour spin drive motor MTR6 is not energized until the bell mandrels have been fully advanced, as detected by the limit switch LS13, and until the molds of the lining cabinet 190 are fully closed as detected by 45 the limit switch LS19. With reference to FIG. 18b, the spin drive motor MTR6 is driven from a motor-generator set 450 whose output is applied to the windings of the motor MTR6 through an automatic acceleration and deceleration control device 452. The control device 452 is 50 under the control of a set of contacts in the relay timer RT3. The relay timer RT3 is connected across the lines X1 and X2 through contacts CR163 of control relay CR16 and the limit switch LS13. Considering that the control relay CR16 was energized when the limit switch 55 LS19 was closed by the closure of the lining cabinet 190, it will be understood that the relay timer RT3 begins its timing and closes its contacts so as to energize the control device 452 at the instant when the molds of the lining cabinet 190 are closed. In response to the closure of the 60 contacts of relay timer RT3, the motor MTR6 is brought up to speed by the control 452.

65 With the spin drive brought up to sufficient speed, the next step in the operation of the spin drive unit is to raise the platform 98 so as to bring the spin drive into engagement with the pipe mold 32. Thus, when the motor MTR6 has been brought up to speed, the normally open contacts RPM21 and RPM22 of an RPM detecting device, connected to the motor MTR6 but not shown, are closed. Through contacts RPM22, contacts CS15 of the 70 Manual-Automatic control switch and through the nor-

mainly closed contacts CR121 of the unenergized control relay CR12, the coil of a control relay CR10 is connected across power lines X1 and X2. The control relay CR10 locks in through its contacts CR101 and through its third set of normally open contacts CR103 the control relay CR10 connects solenoid SV6A across power lines X1 and X2, causing hydraulic fluid under pressure to be applied to the closed end of the cylinder C10, raising the platform 98 into its operative position in which the spin wheel 111 of the drive unit engages the spin band 90 of the pipe mold 32. The raised position of the spin drive unit is detected by closure of a limit switch LS14 which is raised against a stop 454 on the turret 17.

(d) Traversing the measuring and pouring unit into pouring position.—As the spin drive unit is being raised by the hydraulic cylinder C10, the measuring and pouring unit 270 is also being traversed towards the turret 17. Traversal of the measuring and pouring unit 270 towards the turret is initiated by the second set of normally open contacts CR102 of the control relay CR10 which connect the solenoid SV5A across power lines X1 and X2 thus causing the control valve SV5 to apply pressurized fluid to the closed end of hydraulic cylinder C9 which then translates the entire measuring unit 270 towards the turret 17. This movement of the measuring unit 270 continues until the pouring boot 87 enters the mold 32 to a desired extent as indicated by closure of a limit switch LS15 mounted upon the measuring and pouring unit 270. As the measuring and pouring unit reaches its pouring position, the limit switch LS15 is brought up against a stop 456 mounted on a rail 458 upon which the carriage of the measuring and pouring unit rides.

(e) Pouring of metal into the pipe molds.—With the spin drive unit raised to engage the mold spin band 90, the limit switch LS14 closes and begins timing of the relay timer RT3 so as to initiate automatic acceleration and deceleration of the spin drive motor MTR6 by the control unit 452. Then, as the pouring boot 87 is fully extended into the pipe mold 32 and with the molds 32 still spinning at the required speed, the pouring ladle 84 is tilted so as to pour its contents through the pouring boot 87 into the pipe mold 32.

Tilting of the pouring ladle 84 is accomplished by the hydraulic cylinder C8 which is caused to extend its piston rod so as to tilt the ladle 84 when fluid under pressure is applied to it through the control valve SV7. Control valve SV7 is constructed to apply fluid under pressure from the supply line 362 to the closed end of cylinder C8 when its solenoid SV7A is energized. Thus, in order to tilt the ladle 84 when the measuring and pouring unit 270 is in pouring position, the solenoid SV7A is connected across power lines X1 and X2 through the normally open contacts RPM21 of the RPM device associated with the motor MTR6 and through the normally open contacts CR111 of a control relay CR11 which in turn is energized through the limit switch LS15, closed when the measuring and weighing unit 89 has been fully extended.

(f) Dispensing of inoculant into the metal stream.—Referring now to the earlier description of the inoculant dispensing and weigh-out unit 290, it will be recalled that the dispensing of inoculant from the weighing hopper 310 is to begin a short time after the tilting of the pouring ladle 84 so as to assure that the inoculant which is dropped into the pouring boot 87 falls into flowing metal and is thoroughly mixed thereby. Components of the inoculant weigh-out unit are reproduced in FIG. 17a for ease of reference. They include the storage hopper 291 having a funnel-shaped opening at its bottom closed by a clam shell 292; the clam shell may be opened through a set of links 293 by hydraulic cylinder C6.

To open the clam shell 292, fluid under pressure is fed from the supply line 362 to the rod end of cylinder C6 by energization of solenoid SV15B of a control valve SV15. Conversely, the clam shell 292 is closed by ap-

plication of pressurized fluid to the closed end of the cylinder C6 through the control valve SV15 by energization of its solenoid SV15A. Located underneath the hopper 291 so as to receive its contents when the clam shell 292 is open, is the measuring hopper 301 supported upon the arms 303 of an electronic weighing scale 305. For simplicity of explanation, the electronic weighing scale 305 is represented by a limit switch LS17a which functions to indicate the presence of a prescribed amount of inoculant in the weighing hopper 301. In particular, the top one of the arms 303 bears against the limit switch LS17a when the hopper 301 is empty. When the required amount of inoculant is received in the hopper 301, it lowers the rams 303 until the limit switch LS17a is no longer closed by the top one of the arms 303. Sensitivity of the arms 303 to different desired weights in the measuring hopper 301 may be adjusted by changing the amount of torque required to turn the arms enough to open the limit switch LS17a.

20 The hopper 301 has a funneled bottom which opens into the mouth of the pouring boot 87 when the boot is in pouring position. Interposed in the funnel of the hopper 301 is a slidible gate 311 having an opening 312 therein. The slide 311 is actuated by hydraulic cylinder C7 with the slide being in its open position when the hydraulic cylinder C7 is fully retracted by the application of pressurized fluid to its rod end through control valve SV16 due to energization of solenoid coil SV16B. To close the slide 311, solenoid SV16A of the control valve SV16 is energized so as to route fluid under pressure through the control valve SV16 to the closed end of the cylinder C7, thereby extending the rod of the cylinder C7 so as to slide the opening 312 out of alignment with the funnel of the measuring hopper 301.

25 35 To effect energization of solenoid SV16B a short time after the pour ladle 84 has been tilted, the electrical control system includes a delay unit D1 connected across lines X1 and X2 through the normally open contacts CR112 of control relay CR11 so as to begin its timing cycle when tilting of the ladle 84 closes the limit switch LS15. The timing period of delay D1 is set to close its normally open contacts D12 and to open its normally closed contacts D11 about one second after closure of the limit switch LS15 and consequently of the contacts CR112 in series with the delay D1.

30 35 The normally closed delay contacts D11 are connected in series with solenoid SV16A between lines X1 and X2 while normally open contacts D12 of the delay D1 are connected in series with the solenoid SV16B between power lines X1 and X2. Thus, when the delay D1 times out and opens its normally closed contacts D11 and closes its normally open contacts D12, the solenoid SV16 is de-energized and the solenoid SV15B is energized thus causing the cylinder C7 to assume a fully retracted position and the gate 311 to open a short time after the pouring ladle 84 was tilted. As a result, the contents of the inoculant weighing hopper 301 are discharged on top of the flowing metal coursing through the pouring boot 87. Subsequently, after the pouring unit has been retracted from its fully extended position and the limit switch LS15 opens, the delay D1 is reset for its next timing operation.

35 40 45 (g) Returning the measuring and pouring unit to its measuring position.—After the pouring ladle 84 has been fully tilted so as to discharge its contents into the pouring boot 87, it is returned to its level position. Return of the pouring ladle to level position is accomplished in response to closing of the limit switch LS16 situated underneath the lip of the pouring ladle 84. Limit switch LS16 is connected in series with the control relay CR12 between power lines X1 and X2 so that when the pouring ladle 84 is fully tilted and closes the limit switch LS16, the coil of relay CR12 is energized and closes its normally open contacts CR122, connected in series with solenoid SV7B across power lines X1 and X2.

Energization of control relay CR12 also opens its normally closed contacts CR121 connected in series with the coil of control relay CR10, thus deenergizing the relay CR10 and opening its normally closed contacts CR102 and CR103. Since these contacts are respectively connected in series with the solenoids SV5A and SV6A, each of these solenoids is deenergized.

Closure of the contacts CR122 through energization of the control relay CR12 on the other hand energizes the solenoid SV7B. With the solenoid SV7A already deenergized through the previous opening of the contact CR111, the control valve SV7 now applies pressurized fluid to the rod end of the cylinder C8 so as to lower the pouring ladle 84.

(h) Weigh-out of inoculant.—When the ladle 84 has been fully lowered, the next step in the operation of the pouring subunit is to retract the pouring unit from its pouring position to its measuring position and then to initiate the weighing of inoculant for the next pouring cycle. Retraction of the measuring and pouring unit 270 is initiated by closing of the limit switch LS17 located underneath the bottom of the pouring ladle 84 and closed when the ladle is fully lowered (FIG. 17a). The limit switch LS17 is connected in series with the coil of control relay CR13 across power lines X1 and X2 (FIG. 18) and thus causes that control relay to become energized when the pouring ladle 84 is lowered. So energized, the control relay CR13 closes its normally open contacts CR131 and CR132. Through the closed contact CR131, a circuit connecting the solenoid SV5B across the lines X1 and X2 is completed. With solenoid SV5A having been previously deenergized by the opening of contact CR102, the spool of control valve SV5 is shifted and connects the hydraulic supply line 362 to the rod end of hydraulic cylinder C9 causing that cylinder to retract the measuring and pouring unit carriage from the turret 17.

Closing of contact CR132 completes a circuit connecting the coil of control relay CR13A across power lines X1 and X2. The control relay CR13A closes its normally open contact CR13A2 and locks in.

To cause opening of the clam shell 292 so as to initiate weight-out of the inoculant into the measuring hopper 301, the spool of control valve SV15 which controls the hydraulic cylinder C6 associated with the clam shell 292 is shifted by deenergizing the solenoid SV15A and energizing the solenoid SV15B instead. To this end, solenoid SV15A is connected across power lines X1 and X2 through the normally closed contacts CR13A1 of the control relay 13A while the solenoid SV15B is connected across the same power lines through normally open contacts CR13A3 of the control relay. Thus, as control relay 13A is energized, the circuit through solenoid SV15A is interrupted and the circuit through the solenoid SV15B is closed and the clamshell 292 is opened.

In accordance with the principle of operation of the inoculant weigh-out unit, the clam shell 292 is to remain open until sufficient inoculant has been registered in the weighing hopper 301 for bringing the composition of the iron that is to be poured into the pouring boot up to the required level. The weight of inoculant that is to be thus discharged from the storage hopper 291 into the weighing hopper 301 by temporary opening of the clam shell 292 is preselected by setting of the electronic weighing scale 305. As stated earlier, for sake of simplicity the output of the electronic weighing scale is schematically represented by the limit switch LS17a which opens when the weighing arms 303 of the scale 305 are swung down by the requisite weight of inoculant in the measuring hopper 301. Limit switch LS17a is also in series with the coil of control relay CR13A (FIG. 18c) so that when the requisite weight of inoculant has been dropped through the open clam shell 292 into the hopper 301, the control relay CR13A is deenergized, opening its normally closed contacts CR13A1 so as to deenergize solenoid SV15A and closing its normally closed contacts CR13A3 so as to

energize the solenoid SV15B. This again reverses the position of the spool of control valve SV15 and causes application of fluid under pressure from the supply line 362 to the closed end of the cylinder C6 thus closing the hopper 292.

With the completion of the weigh-out of inoculant the operation of the pouring subunit is completed. While inoculant was being weighed out for the next pouring operation, the lining which was being formed in the bell mandrel lining station cured and indexing of the turret plate 186 is about to begin. This step and the control apparatus for accomplishing it will now be described.

(i) Indexing the bell mandrels.—During the earlier description in section C-4-b of the first portion of the bell mandrel coating subunit, the last event was indicated to be the setting of the timer RT4 (FIG. 18c) so as to time the subsequent retraction of the extruder 195 and the opening of the lining cabinet 190 to occur when the lining on the bell mandrels has cured (FIG. 17b). Assuming that the time required to cure the linings on the bell mandrels in the lining cabinet 190 has elapsed and that the timer RT4 has run down, it follows that the timer contacts RT41 open and timer contacts RT42 close. Opening of the contacts RT41 interrupts the circuit which had connected solenoid SV10A across power lines X1 and X2. As a result, the spring loaded spool of the control valve SV10 is shifted down and the control valve SV10 connects the hydraulic supply line 362 to the rod end of the cylinder C16 causing the extruder 195 to be withdrawn from the molding cabinet 190. At the same time, the normally open contacts RT42 of the timer RT4 complete a circuit connecting the coil of control relay CR17 across power lines X1 and X2. Through its normally open contacts CR171 control relay CR17 completes a circuit connecting solenoid SV9B across the lines X1 and X2. At the same time through its normally closed contacts CR172 connected in series with solenoid SV9A between power lines X1 and X2, control relay CR17 deenergizes the solenoid SV9A so that the spool of the control valve SV9 shifts and the hydraulic supply line 362 is connected through the control valve SV9 to the rod end of the hydraulic cylinder C15, causing the lining molds 19 to open.

With the molds 191 fully open, the next step is to withdraw the mandrels 182 and 184 from the pipe molds 32 in the turret and from the lining cabinet 190. It will be noted that withdrawal of the mandrels 182 from the molds 32 in the turret 17 is appropriate at this point since the pouring of the pipe into the molds has been completed and metal is held by centrifugal force against the inner walls of the pipe molds 32.

Retraction of the mandrels 182 and 184 together with their associated turret plate 186 is achieved by connecting the hydraulic supply line 362 through the control valve SV8 to the rod end of the control cylinder C12. To this end, the spool of the control valve SV8 is shifted by energizing solenoid SV8B and by deenergizing solenoid SV8A. As seen in FIG. 18c, solenoid SV8A is connected across power lines X1 and X2 through normally open contacts CR142 of control relay CR14 while SV8B is energized through the normally open contacts CR184 of the control relay CR18. Control relay CR18 is energized by the power lines X1 and X2 through the limit switch LS20 which is closed by an extension 460 on one of the lining molds 191 when the molds are fully opened. Consequently, when the molds 191 are thus opened, limit switch LS20 closes, energizing control relay CR18 which through its contacts 184 actuates solenoid SV8B. Additionally, through its normally closed contacts CR183, connected in series with the locking-in contact CR141 of the control relay CR14, the control relay CR18 causes control relay CR14 to drop out and to open its contacts CR142 so as to deenergize solenoid SV8A. With the solenoid SV8A deenergized and with the solenoid SV8B energized, control valve SV8 applies pressurized fluid in the

required manner from the supply line 362 to the rod end of the hydraulic cylinder C12 which then retracts the turret plate 186.

At this time the pour unit spin drive is to be disengaged by lowering its platform 98. To this end, the solenoid SV6B is connected across lines X1 and X2 through the normally open contacts CR181 of control relay CR18. As these contacts close in response to the energization of control relay CR18 through limit switch LS20, solenoid SV6B is energized connecting the hydraulic supply line 362 to the rod end of hydraulic cylinder C10 which then lowers the platform 98 (FIG. 17a).

Returning to the sequence of events in the mandrel lining subunit, after the mandrels have been fully retracted, they are to be rotated 180° so as to bring the line mandrels into position for insertion into pipe molds 32 during the next pouring cycle and so as to bring the used mandrels down into position for re-lining in the lining cabinet 190.

To cause the mandrels 182 and 184 to exchange positions they are mounted on an indexible turret plate 186. The plate 186 is moved laterally towards and away from the turret 17 by the shaft 185 of the hydraulic cylinder C12. Indexing of the mandrels 182 and 184 is achieved by rotating the turret plate 186 through an arc of 180° thus causing the top and bottom mandrel pairs to exchange positions. For this purpose, a rotatably mounted indexing plate 187 is provided. The indexing plate 187 is generally circular and has an internally splined bushing 183 at its center.

The shaft 185 upon which the turret plate 187 rests for lateral travel toward and away from the turret 17 extends through the bushing 183 and has a splined hub 185a at its end nearest the turret plate 186. With the turret plate 186 fully retracted by the cylinder C12, the splined hub 185a of the shaft 185 enters and engages the internally splined bushing 183 of the indexing plate 187. With the indexing plate 187 thus interlocked with the indexible turret plate 186, the turret plate 186 can be rotated about its axis by rotating the indexing plate 187. The indexing plate 187 is rotated into either one of two positions corresponding to the two operative positions of the turret plate 186 by a pair of hydraulic cylinders C11 and C13 which are connected to the hydraulic lines 362 and 364 through control valve SV11. To place the indexing plate 187 and the turret plate 186 carried with it in their first position, wherein the mandrels 182 are on top and the mandrels 184 are at the bottom, solenoid SV11A of the control valve SV11 is energized, causing the hydraulic supply line 362 to be connected to the rod ends of the cylinders C11 and C13. To place the indexing plate 187 and the turret plate 186 into their second position, 180° removed from their first position, the solenoid SV11B is energized connecting the hydraulic supply line 362 to the closed ends of the cylinders C11 and C13.

The positions of the mandrels 182 and 184 on the turret plate 186 are interchanged for each pouring operation so as to bring spent mandrels into the lining cabinet and lined mandrels into pouring position by successively energizing alternate ones of the solenoids SV11A and SV11B. For this purpose, a pair of limit switches LS21 and LS22 are mounted on the indexing plate 187. The rear face of the indexing plate 187 is so configured that when the turret plate 186 is retracted, with the mandrels 182 on top and the mandrels 184 below them, the indexing plate 186 closes the limit switch LS22 but not the limit switch LS21. On the other hand, when the turret plate 186 is withdrawn with the mandrels 182 at the bottom and the mandrels 184 at the top, the limit switch LS21 is closed and the limit switch LS22 remains open.

As seen in FIG. 18d, the limit switch LS21 is connected in series with the coil of control relay CR19 whose normally open contacts CR191 complete a circuit connecting solenoid SV11A across power lines X1 and X2. Similarly, limit switch LS22 is connected with the coil of control relay CR20 with the normally open contacts

5 of that relay completing a circuit which connects the solenoid SV11B across the power lines X1 and X2. Consequently, when the turret plate 186 is retracted in its first position so that it closes the limit switch LS22 solenoid SV11B is energized applying fluid under pressure to the closed ends of cylinders C11 and C13 so as to rotate the indexing plate 187 and the turret plate 186 into their second position. Conversely, when the turret plate 187 is withdrawn the next time and the limit switch LS21 is closed thereby, solenoid SV11A will be energized applying pressurized fluid to the rod ends of cylinders C11 and C13 causing those cylinders to return the indexing plate 187 and the turret 186 with it into their original position.

15 (5) The pipe cooling station

The hydraulic system for traversing the internal cooling units into and out of the turret is shown in FIG. 17b. A pair of cooling units 210 of the type shown in FIG. 15 are mounted on a carriage 462 which rides on a rail 464. The cooling units are so mounted upon the carriage 462 that when the carriage completes its travel towards the turret 17, the cooling units enter the two molds located in the cooling station.

20 The carriage 462 is traversed along the rail 464 by a hydraulic cylinder C17 which is under the control of the valve SV12. The spindle of the control valve SV12 is spring biased downward so as to open a path through the valve from the supply line 362 of the hydraulic system to the rod end of cylinder C17. This retracts the piston of cylinder C17 and with it the carriage 462 so as to withdraw the cooling units 210 from the molds in the turret 17. Valve SV12 has a single solenoid SV12A which when energized lifts the spindle of the valve so as to connect the head end of the cylinder C17 to the hydraulic supply line 362 and the rod end of the cylinder C17 to the return hydraulic line 364. With the solenoid SV12A thus energized, the piston of cylinder C17 extends fully so as to move the carriage 462 towards the turret 17 and the cooling units 210e and 210f into their spraying position within the molds in the turret.

25 The electrical control circuitry for inserting the cooling units 210e and 210f into the molds 32 and for controlling the spray control valves 211 during the cooling cycle is shown in FIG. 18d. One terminal of the solenoid 30 SV12A is connected to the power line X2. The other terminal of the solenoid is connected to the power line X1 through two parallel paths, one path including the contact CR21e1 of the control relay CR21e and the other path including the normally open contact CR21f1 of control relay CR21f. The control relays CR21e and CR21f are those described earlier in connection with the control systems for shutting the control valves 211 during release of latent heat by the cast pipe in the cooling station. When energized, control relay CR21e, through its normally open contacts CR21e3 applies power to the open control valve 211e with which it is connected in series between the lines X1 and X2. Similarly, the control valve 211f is turned on when the control relay CR21f is energized by normally open contacts CR21f3 of the control relay, connected in series with the control valve between power lines X1 and X2.

35 The coils of both control relays CR21e and CR21f are energized by contacts of the limit switch LS25 upon indexing of a set of molds by the turret into the cooling station. Thus, the coil of relay CR21e is connected between lines X1 and X2 through contacts LS25-1 of the limit switch LS25 while the coil of control relay CR21f is similarly connected between the lines X1 and X2 through contacts LS25-2 of the same limit switch.

40 Upon indexing of a pair of molds into the cooling station, the control relays CR21e and CR21f are pulled in, and lock in through their contacts CR21e2 and CR21f2 respectively, each of which is connected in series with the coil of its relay between the lines X1 and X2. With the

relays CR21e and CR21f pulled in, their contacts CR21e1 and CR21f1 also close and energize the solenoid SV12A, causing the hydraulic supply line 362 to be connected through the valve SV12 to the closed end of the cylinder C17 which in turn traverses the cooling unit carriage 462 towards the turret 17.

Connected in series with the lock-in contacts CR21e2 are the contacts 233e1 of the reset timer 233e and in a similar manner contacts 233f1 of the reset timer 233f are connected in series with the lock-in contacts CR21f2 of the relay CR21f. These timers, discussed in section B-2 with reference to FIG. 14, serve to deenergize the control relays when it is desired to reduce the rate at which the cast metal pipe is cooled in the molds. Timer 233e is connected across lines X1 and X2 through the delay contacts 232e1 of the internal metal cooling control 230e of the cooling station E, which is responsive to the pipe internal temperature sensor 220e. Similarly, the temperature in the cooling station F is sensed by a sensor 220f whose output is fed to a temperature control unit 230f including a delay having a set of normally open contacts 232f1 connected in series with the timer 233f between the power lines X1 and X2. As earlier described in reference to FIG. 14, each delay contact is caused to close a short time after the cast metal internal temperature detected by its associated sensor 220 has come to rest at the level at which the metal releases its latent heat.

When the delay contacts 232e1 become closed, the timer 233e begins its timing cycle and a predetermined time later opens its contacts 233e1 causing the control relay CR21e to drop out and to open its contacts CR21e1. At some different time, determined by the instant when the cast metal pipe in the cooling station F begins to release its latent heat, the delay contacts 232f1 close and at some time later the timer 233f opens its contacts 233f1 so as to deenergize the relay CR21f, opening its contacts CR21f1.

It will be noted that the solenoid SV12A is energized so long as either of the spray units 210e or 210f continue to propel coolant into a pipe within the turret 17. Only when both timers 233e and 233f have timed out, indicating that both spray units 210e and 210f have completed their cooling cycles is the solenoid SV12A deenergized. When this occurs, the control valve SV12 raises its spool and again connects the hydraulic supply line 362 to the rod end of cylinder C17, retracting the cooling carriage 462.

(6) The pipe extracting station

The pipe extracting subunit which was earlier described in connection with FIG. 1 includes a carriage 138 which moves on a track 140 towards or away from the turret 17. With particular reference to FIG. 17b, showing a hydraulic system for controlling the motion of the pipe extractor mechanism, the carriage 138 is moved on its tracks by means of a hydraulic cylinder C19 under control of a double acting solenoid actuated control valve SV13. To move the carriage 138 towards the turret 17, solenoid SV13A is actuated, thereby connecting the hydraulic supply line 362 to the closed end of the cylinder C19, causing the cylinder to extend its piston so as to push the carriage towards the turret 17. To retract the carriage 138 away from turret 17, the solenoid SV13B is energized after the solenoid SV13A has been deenergized thereby applying pressurized fluid to the rod end of cylinder C19 while returning fluid from the closed end of the cylinder to the return hydraulic line 364.

Mounted upon the carriage 138 is a hydraulically actuated gripping device 132 comprising a set of tongs 134 and a hydraulic cylinder C18 for opening and closing the tongs. Thus to extract a pipe from within a mold in the extracting station the extractor carriage 138 is advanced until the gripping tongs 134 are within the bell end of the pipe as shown in FIG. 17b. Once within the pipe, the tongs are opened so as to grippingly engage the

inner wall of the pipe and at the same time the carriage is retracted, pulling the pipe out of the mold 32 in the turret 17.

The tongs 134 of the gripping device 132 are rockably mounted and are connected through a set of links to a control shaft operated by the hydraulic cylinder C18 in such a manner that they may be opened or closed by application of pressurized fluid to the closed end or the rod end of the cylinder C18. To open the tongs 134, the rod end of the cylinder C18 is connected through the control valve SV14 to the hydraulic supply line 362 by energizing solenoid valve SV14A. To close the tongs 134, solenoid SV14B is energized causing the valve SV14 to connect the hydraulic supply line 362 to the closed end of the cylinder C18 thereby positioning its piston in its fully extended position so as to close the tongs 134.

Also mounted on the carriage 138 is a temperature sensor 142 which upon detecting the hot pipe in the mold 32 signals to the electrical control system of the pipe extracting subunit that the tongs are within the pipe that is to be extracted and that the tongs are to be opened.

Turning now to the electrical control system of the pipe extracting station, shown in FIG. 18d, the solenoids SV13A and SV13B of the control valve SV13 are controlled by three control relays CR22, CR23, and CR24. The solenoid SV13A is energized through the normally open contacts CR221 of control relay CR22 and through the normally closed contacts CR231 of the control relay CR23. The winding of control relay CR22 is connected across lines X1 and X2 through the contacts CS18 of the manual automatic control switch CS1 and through the limit switch LS27 which is tripped by a stop 462 on the turret 17 when a new set of molds are indexed into the extracting station. The first event which occurs in the pipe extracting station is the energization of relay CR22 due to the tripping of the limit switch LS27 as a new pair of molds are indexed into the extracting station. Relay CR22 locks itself in through its contacts CR222 which by-pass the limit switch LS27 and through the normally open contacts CR221 the solenoid SV13A is energized and hydraulic fluid pressure is applied by the control valve SV13 to the closed end of cylinder C19 causing the carriage 138 to be pushed towards the turret 17.

In accordance with the invention, the gripping tongs 134 are to open and the carriage is to retract automatically when the tongs have advanced to their gripping position within the pipes held in the molds on the turret. To this end, the temperature sensor 142 is provided with a relay having a set of contacts BT1 which close when the temperature sensor 142 is brought within proximity of the hot pipes to be extracted. Contacts BT1 are connected in series with relay CR23 completing a circuit through the relay across the lines X1 and X2. Thus when the tongs are within the pipes to be extracted, the temperature sensor 142 through its contacts BT1 energizes the winding of relay CR23.

In response to the energization of relay CR23, the gripping tongs are immediately opened in the following manner. Through its normally open contact CR232, the relay CR23 completes a circuit connecting the solenoid SV14A across the power lines X1 and X2 energizing that solenoid. At the same time due to opening of its normally closed contacts CR233, the control relay CR23 interrupts a circuit which previously connected the solenoid SV14B across the power lines X1 and X2. As a result, the spool of the control valve SV14 shifts and the hydraulic supply line 362 is connected through the control valve SV14 to the rod end of the cylinder C18 causing the gripping tongs 134 to open.

At the same time as the gripping tongs 134 open to engage the pipe in the mold 32, the travel of the carriage 138 is reversed so as to begin the extracting of the pipe from the mold. The relay connections which achieve this reversal will now be briefly described.

As the control relay CR23 is energized, its normally open contacts CR234 complete a circuit which connects the winding of control relay CR24 across the power lines X1 and X2. The normally open contacts CR241 of a control relay CR24 in turn complete another circuit which connects the solenoid SV13B across the power lines X1 and X2, thus causing that solenoid to be actuated as the control relay CR24 is energized through the contacts CR234 of the control relay CR23. Solenoid SV13A, on the other hand, is deenergized at the same time due to the opening of the normally closed contacts CR231 of the control relay CR23 which is connected in series with that solenoid. As a result, the spool of the control valve SV13 also shifts and the hydraulic supply line is connected through the control valve SV13 to the rod end of the cylinder C18 causing the pipe extracting carriage 138 to be retracted and the pipe to be extracted by means of the tongs 134 from the mold 32.

In accordance with a further feature of the invention, means are provided for reversing the extractor carriage 138 and for closing tongs 134 in the event that they should slip out of the pipe during the extracting step. In such an event the closed tongs are caused to re-enter the pipe within the mold 32 and then to expand again to re-engage the pipe at which time the carriage is caused to resume its rearward journey and the extracting process is continued.

So long as the hot pipe remains on the gripping tongs 134, its presence is sensed by the temperature sensor 142 and the extracting process continues. As soon, however, as the pipe slips off the tongs 134, its separation from the carriage 138 is detected by the sensor 142 which opens its contact BT1 as a result. Opening of the sensor relay contact BT1 drops out the relay CR23. Closing of the normally closed contact CR233 reenergizes the solenoid SV14B and the opening of the normally open contact CR232 deenergizes the solenoid SV14A. As a result, the control valve SV14 reverses the application of pressurized fluid to the cylinder C18 causing the gripping tongs 134 to be closed.

Similarly, opening of the relay contacts CR234 deenergizes control relay CR24 opening its contacts CR241 so as to deenergize solenoid SV13B. At the same time, solenoid SV13A is reenergized due to the closing of normally closed contacts CR231. Consequently, the control valve SV13 also reverses the flow of pressurized fluid through the cylinders C19 causing the carriage 138 to be returned to the pipe that was left behind by the extracting mechanism. When the pipe is reached and the tongs 134 enter it, the sensor 142 detects the presence of the hot pipe, closes its relay contacts BT1, and the process of opening the tongs and retracting the extracting carriage 138 is repeated.

Although it is not expected that the pipe will slip off the tongs 134 more than once during an extracting cycle, it may be seen that should this event occur, the extracting mechanism will continue to return the tongs into the pipe so as to reestablish its grip upon the pipe until the pipe has been fully extracted from the mold 32.

The extracting subunit is so designed that the pipe is fully extracted from its mold shortly before the extracting unit has been fully retracted so as to permit the closing of the tongs 134 at that time. This permits the tongs to be removed from within the pipe during the final portion of the extracting cycle so that they will not interfere with the subsequent removal of the pipe from the extracting station. For this purpose, a limit switch LS28 is connected in series with the circuit of solenoid SV14A and this limit switch LS28 is maintained in closed position by an extension 464 until the carriage reaches within a predetermined distance of its fully retracted position. At this time the limit switch LS28 opens and causes the solenoid SV14A to be deenergized. As a result, the tongs 134 no longer press against the pipe and the carriage 138 completes its rearward travel by withdrawing the gripping tongs from within the pipe.

An additional limit switch LS26 is mounted in the path of carriage 138 and is closed thereby when the carriage is fully retracted. The limit switch LS26 is connected in series with the solenoid SV13B through the contacts CR241 and consequently as the carriage reaches its fully retracted position, opening of the limit switch LS26 completely de-energizes the control valve SV13 completing the operation of the pipe extracting subunit.

I claim as my invention:

1. In a machine for the centrifugal casting of pipe or the like the combination of:
  - (a) a base,
  - (b) a turret rotatably mounted on said base,
  - (c) a plurality of molds rotatably mounted on said turret about the periphery thereof,
  - (d) a plurality of operating stations disposed around said turret and spaced apart by the same distance as said molds so that each of said stations is in register with said molds at the same time,
  - (e) drive means for rotating said turret to index said molds from station to station,
  - (f) a first one of said stations including means responsive to the indexing of a mold at such station for coating the inner wall of the mold indexed at said first station,
  - (g) a second one of said stations including means responsive to the indexing of a mold at such station for spinning the mold at such station and pouring a predetermined quantity of molten metal into the spinning mold so that the molten metal is centrifugally spread over the coating on the inner wall of said mold,
  - (h) a third one of said stations including means responsive to the indexing of a mold at such station for cooling the cast metal in said mold by spraying a coolant into one end of said mold and withdrawing said coolant from the other end of said mold,
  - (i) a fourth one of said stations including means responsive to the indexing of a mold at such station for removing the cast article from the mold, and
  - (j) a cooling system within said turret for maintaining the outer walls of the molds at said first, second, and third stations at a substantially constant temperature so as to extend the mold life and improve the uniformity of the cast articles, said cooling system including:
    - (1) means for individually detecting the outer wall temperatures of the molds at said first, second, and third stations, and
    - (2) means responsive to said detecting means for individually spraying the outer wall of any one of the molds at said first, second, and third stations when the wall temperature of that mold as detected by its associated detecting means exceeds a predetermined maximum.
2. The combination of claim 1 wherein said cooling system includes means for individually detecting the temperature and cooling the surface of each said mold at said first, second, and third stations at distinct zones distributed along the longitudinal axes of said molds, so as to keep the temperature of said molds uniform along their length.
3. The combination of claim 2 wherein said cooling system for individual cooling of several mold zones includes for each zone of a mold at said first, second, and third stations, means for detecting the temperature of that zone, means for spraying cooling fluid at said zone, and valve means associated with said spraying means for applying cooling fluid to said spraying means in response to a signal from the temperature detecting means when the temperature of said zone exceeds a predetermined limit.
4. The combination of claim 1 wherein said means for cooling the cast metal includes means for directing a spray of cooling fluid into one end of the mold, valve means connected to said spraying means and to a source of cooling

fluid for selectively applying cooling fluid to said spraying means, temperature sensing means for detecting the temperature of the cast metal in the mold, and control means connected between said temperature sensing means and said valve means for shutting said valve means a predetermined time after the temperature detected by said detecting means has dropped to the latent heat releasing temperature of said cast metal.

5 5. The combination of claim 1 wherein said means for cooling cast metal in a mold located in said third station includes means for turning off said spraying means while said mold is still in said third station before the metal in said mold has given up its latent heat of fusion so as to prevent chilling of said cast metal.

10 6. In a machine for centrifugal casting of pipe or the like the combination of:

- (a) a base,
- (b) a turret rotatably mounted on said base,
- (c) a plurality of molds rotatably mounted on said

20 turret about the periphery thereof,

- (d) a plurality of operating stations disposed around said turret and spaced apart by the same distance as said molds so that each of said stations is in register with said molds at the same time,

- (e) drive means for rotating said turret to index said molds from station to station,

- (f) a first one of said stations including means responsive to the indexing of a mold at such station for coating the inner wall of the mold indexed at said first station,

- (g) a second one of said stations including means responsive to the indexing of a mold at such station for spinning the mold at such station and for concurrently pouring a predetermined quantity of molten metal into said mold so that the molten metal is centrifugally spread over the coating of the inner wall of said mold,

- (h) a third one of said stations including:

- (1) means responsive to the indexing of a mold at such station for cooling the cast metal in said mold at an initial rate which is in excess of the chill-inducing cooling rate of said metal in the solid state and at a second diminished rate which is not in excess of the said chill-inducing rate,

- (2) means for sensing the temperature of said cast metal,

- (3) control means connected to said temperature sensing means and to said cooling means for reducing the rate of said cooling means to its diminished rate in response to said temperature sensing means a predetermined time after the temperature detected by said sensing means has dropped to the latent heat releasing temperature of said cast metal, and

- (i) a fourth one of said stations including means responsive to the indexing of a mold at such station for removing the cast articles from the mold.

7. The combination of claim 6 wherein said predetermined time is selected to occur when said cast metal has given up most of its latent heat of fusion.

8. In a machine for the centrifugal casting of pipe or the like the combination of:

- (a) a base,
- (b) a turret rotatably mounted on said base,
- (c) a plurality of molds rotatably mounted on said

55 turret about the periphery thereof,

- (d) a plurality of operating stations disposed around said turret and spaced apart by the same distance as said molds so that each of said stations is in register with said molds at the same time,

- (e) drive means for rotating said turret to index said molds from station to station,

- (f) a first one of said stations including means responsive to the indexing of a mold at such station

for coating the inner wall of the mold indexed at said first station,

(g) a second one of said stations including means responsive to the indexing of a mold at such station for spinning the mold at such station and for pouring a predetermined quantity of molten metal into said mold so that the molten metal is centrifugally spread over the coating of the inner wall of said mold,

(h) a third one of said stations including means responsive to the indexing of a mold at such station for cooling the cast metal in said mold at a high rate by spraying coolant into one end of said mold and withdrawing said coolant from the other end of said mold,

(i) a fourth one of said stations including means responsive to the indexing of a mold at such station for removing said cast articles from the mold,

(j) a cooling system within said turret for maintaining the outer walls of the molds at said first, second, and third stations within predetermined temperature limits so as to extend mold life and improve the uniformity of the cast articles,

(k) said third station additionally including means for turning off said cooling means while said mold is still in the third station before the metal in said mold has given up its latent heat of fusion so as to prevent excessive chilling of said cast metal.

9. The combination of claim 8 wherein said second one of said stations includes means for injecting a measured amount of inoculant into the stream of molten metal flowing into said mold.

10. The combination of claim 8 wherein said mold cooling means is set to remove heat from the cast pipe in the cooling station at a rate which does not cause the pipe to chill excessively while it is solidifying and wherein said means for cooling cast metal in a mold indexed in said third station includes means for setting the rate at which cooling fluid spray is applied at a level which removes heat from said metal at a rate which would cause excessive chilling if continued after the pipe had solidified, and means for turning off said cooling means before said metal has given up its latent heat of fusion, so as to cool the metal at a high rate while it is in liquid form without exceeding the rate of cooling which the metal can tolerate in the solid state without excessive chilling.

11. The combination of claim 10 wherein said means for turning off the cooling means includes:

(a) means for detecting when said cast metal has dropped to the temperature at which it liberates its latent heat of fusion, and

55 (b) means responsive to said detecting means for interrupting said cooling means a predetermined time after said condition has been reached, said predetermined time being set to fall before the time when said cast metal has liberated all of its latent heat of fusion so as to insure that before the metal has solidified, the rate of cooling of said cast metal is reduced to a rate which the metal can tolerate in the solid state without excessive chilling.

12. The combination of claim 8 wherein said means for cooling the hot cast metal in said third station includes means at said third station directed at one end of the mold at said station for projecting intermittent bursts of water at high pressure into said cast metal and exhaust means at said third station near the other end of said mold for establishing an air stream in said mold from said one end to said other end so as to cause rapid propagation along said cast metal interior of stream rings generated by the impinging of said water bursts upon said hot cast metal.

13. The combination of claim 8 wherein said cooling system includes means for individually cooling each of said molds at a predetermined rate when and only when its temperature exceeds a predetermined maximum and

wherein said means for cooling the cast metal in said third station includes means for spraying cooling fluid into the mold in said station at a preset rate and means for turning off said spraying means after the cast metal has given up a part of its latent heat of fusion.

14. The combination of claim 8 wherein said second station includes:

- (a) a pouring ladle,
- (b) means responsive to the indexing of a mold at said station for charging said pouring ladle with a predetermined amount of molten metal,
- (c) means responsive to the spinning of said mold for initiating the pouring of molten metal from the pouring ladle into the mold at the pouring station, and
- (d) means responsive to the initiation of said pouring to apply an inoculant to the following metal in an amount sufficient to increase the carbon equivalent of the metal as poured to a level at which the metal has a predetermined freezing temperature.

15. In a machine for manufacturing iron castings, a system for solidifying castings at a high rate without chilling them comprising:

- (a) a mold for receiving a charge of molten iron,
- (b) means for extracting heat from said iron at a high initial rate and at a diminished rate which permits the iron to cool without excessive chilling,
- (c) means for sensing the temperature of said molten iron, and
- (d) control means connected to said temperature sensing means and to said heat extracting means for setting the rate of said means to its diminished rate in response to said temperature sensing means a predetermined time after the temperature detected by said sensing means has dropped to the temperature of latent heat release for said molten iron.

16. The system of claim 15 wherein said predetermined time is selected to occur when said molten iron has given up most of its latent heat of fusion.

17. In a machine for manufacturing castings, a system for solidifying hollow castings at a high rate without chilling them comprising:

- (a) a mold for receiving molten metal,
- (b) means for measuring out a predetermined amount of hypoeutectic metal,
- (c) means for inoculating said metal just before it is poured by an amount of inoculant sufficient to make said metal eutectic so as to improve its structure and so as to give it a predetermined freezing temperature,
- (d) means for spinning said mold,
- (e) means for pouring the eutectic metal into the spinning mold,
- (f) first means for cooling the cast metal by removing heat from said metal through its inner surface, said means having a rate which is substantially higher than that which the metal could tolerate without chilling if were subjected to said rate after it had begun to solidify, and second means for cooling said cast metal by removing heat from said metal through said mold at a diminished rate which does not cause excessive chilling in the metal,
- (g) means for sensing the temperature of the inner surface of said cast metal,
- (h) means for sensing the temperature of said mold,
- (i) first control means connected to said metal temperature sensing means and to said first cooling means for shutting down said cooling means a predetermined time after the metal has dropped to its predetermined freezing temperature, and
- (j) second control means connected to said mold temperature sensing means and to said second cooling means for actuating said cooling means in response to the rise in mold temperature following the shutting down of said first cooling means.

18. The system of claim 17 wherein said predetermined

5

70

75

time is selected to occur when said cast metal has given up a substantial part of its latent heat of fusion.

19. In a machine for automatic manufacture of centrifugal castings, the combination comprising:

- (a) a mold mounted for rotation about its longitudinal axis,
- (b) means for spinning said mold and for applying a refractory lining to its interior wall while the mold is spinning,
- (c) means responsive to the completion of said coating operation for pouring a predetermined amount of metal having a known temperature of latent heat release into said mold while it is still spinning,
- (d) means responsive to the completion of said pouring operation for cooling said centrifugally cast metal in said mold, said cooling means having a first, high cooling rate and a second, low cooling rate,
- (e) means for sensing the temperature of said cast metal while it is being cooled,
- (f) means for initiating operation of said cooling means at its high cooling rate when the cast metal temperature is in excess of its solidification temperature, and
- (g) control means responsive to said temperature sensing means for setting said cooling means to its second, lower cooling rate a predetermined time after said cast metal has dropped to its temperature of latent heat release.

20. Claim 19 wherein said predetermined time is less than that required for the cast metal to give up all of its latent heat of fusion.

21. The machine of claim 20 additionally including:

- (a) means for measuring out a predetermined amount of hypoeutectic metal to said pouring means, and
- (b) means responsive to the completion of the coating operation for adding an inoculant to said measured hypoeutectic metal, while it is being poured, in an amount sufficient to make said metal, as cast, eutectic.

22. In a machine for automatic manufacture of centrifugal castings, the combination comprising:

- (a) a mold mounted for rotation about its longitudinal axis,
- (b) means for spinning said mold and for applying a refractory lining to its interior wall while the mold is spinning,
- (c) means responsive to the completion of said coating operation for pouring a predetermined amount of metal having a known temperature of latent heat release into the mold while it is still spinning,
- (d) first means for cooling the cast metal by removing heat from said metal through its inner surface at a high rate,
- (e) second means for cooling said cast metal by removing heat from said metal through said mold at a lower rate,
- (f) means for sensing the temperature of the inner surface of said cast metal,
- (g) means for sensing the temperature of the exterior of said mold,
- (h) first control means connected to said metal temperature sensing means and to said first cooling means for shutting down said cooling means a predetermined time after the metal has dropped to its temperature of latent heat release, and
- (i) second control means connected to said mold temperature sensing means and to said second cooling means for actuating said cooling means in response to the rise in mold temperature following the shutting down of said first cooling means.

23. The combination of claim 22 wherein the metal poured by said pouring means is iron, wherein said cast iron cools under the effect of said first cooling means at a rate which is in excess of 30° F./second and wherein said cast iron cools under the effect of said second cooling means at a rate which is not in excess of 15° F./second.

24. In an automatic casting machine wherein hollow articles are centrifugally cast in tubular molds, a self-correcting article extractor for removing the cast articles from the molds including:

- (a) a set of expandable tongs,
- (b) proximity sensing means for detecting when said tongs are within said article,
- (c) means responsive to said proximity detecting means for traversing said tongs in closed condition towards and into said cast article when said proximity detecting means indicates that said tongs are not within said article, and
- (d) means responsive to said proximity detecting means for expanding said tongs so as to grip said article, and
- (e) means responsive to said proximity detecting means for retracting said expanded tongs with said article when and only so long as said proximity detecting means indicates that said tongs are within said article,
- (f) said traversing means, retracting means and tong expanding means being operative to repeat the process of traversing toward and grippingly expanding into said article and then retracting said article every time said gripping tongs slip out of the end of said cast article so as to automatically withdraw said article fully from said mold regardless of the loss of grip upon the article by said tongs.

25. A device for casting an enlarged portion on the end of a centrifugally cast pipe coincident with the casting thereof, comprising a mold, having an end thereof enlarged, said mold being rotatably mounted in a turret, a core mandrel adapted to engage said enlarged end to form a tight closure, a swingable plate adjacent said mold for mounting said core mandrel and moving the same between said mold and means defining a lining cavity, a plurality of heating burners disposed adjacent said cavity, means for extruding a refractory lining on said core mandrel when the same is fitted in said cavity.

26. In a machine for the centrifugal casting of pipe or the like, the combination of a base, a turret rotatably mounted on said base, a plurality of mold groups rotatably mounted on said turret about the periphery thereof with substantially equal spacing between adjacent mold groups, a plurality of operating stations disposed around said turret and spaced apart by the same distance as said mold groups so that each of said stations is in register with a mold group at the same time, drive means for rotating said turret to index said mold groups from station to station, a first one of said stations including means responsive to the indexing of a mold group at such station for applying a uniform coating of a mixture of refractory

material and binder material on the inner wall of the molds indexed at said first station, a second one of said stations including means responsive to the indexing of a mold group at such station for spinning the molds in that group about their longitudinal axes and simultaneously pouring a predetermined quantity of molten metal into said molds so that the molten metal is centrifugally spread over the refractory coatings on the inner walls of said molds, a third one of said stations including means responsive to the indexing of a mold group at such station for cooling the centrifugally cast metal in said group by spraying a cooling fluid into one end of each mold and withdrawing said fluid from the other end of each mold, a fourth one of said stations including means responsive to the indexing of a mold group at such station for removing the centrifugally cast articles from the molds, a cooling system within said turret for maintaining the outer walls of only the molds at said first, second, and third stations at a substantially constant temperature so as to extend the mold life and improve the uniformity of the cast articles, and bell forming mechanism associated with said second station and responsive to the indexing of a mold group at such station for inserting a first set of refractory coated bell forming cores in one end of the molds in that group, said mechanism including means for coating a second set of bell forming cores with refractory material and means for reversing the positions of said first and second sets of bell forming members upon each successive indexing movement of said turret.
